UNITED STATES PATENT OFFICE

2,450,165

CASH REGISTER

Harold O. Randall, Dayton, Ohio, and John B. Geers, deceased, late of Dayton, Ohio, by John H. More, administrator, Cincinnati, Ohio, assignors to The National Cash Register Company, Dayton, Ohio, a corporation of Maryland

Application June 3, 1943, Serial No. 489,516

24 Claims. (Cl. 235—3)

1

The present invention relates to combined cash registers and adding machines and is particularly directed to novel means for controlling the engagement and disengagement of the totalizers and the actuators and for controlling the shifting of the totalizers to effect selection thereof.

The machine to which the present invention is herein shown applied is of the type illustrated and described in the application for Letters Patent of the United States, Serial No. 430,214, filed February 10, 1942, by Edward J. Carey et al., for Cash registers (Patent No. 2,443,652 dated June 22, 1948). Such machine also embodies features disclosed in United States Patent No. 2,286,116 for Cash registers, which issued on June 9, 1942, to Bernis M. Shipley, and the United States Patent No. 1,693,279, issued on November 27, 1928, to Walter J. Kreider.

It is a primary object of the invention to provide novel means for controlling the shifting of the totalizers to effect the proper selection thereof when the machine is used either as a cash register or an adding machine.

Another object of the invention is to provide novel means for controlling the shifting of the totalizers and the selective engagement and disengagement of the totalizers and amount actuators to clear an amount from one totalizer and enter this amount on another totalizer during a single operation of the machine.

With these and incidental objects in view, the invention includes certain novel features of construction and combinations of parts, the essential elements of which are set forth in appended claims, and a preferred form or embodiment of which is hereinafter described with reference to the drawings which accompany and form a part of this specification.

In the drawings:

Fig. 1 is a diagrammatic view of the keyboard of the machine embodying the present invention.

Fig. 2 is a facsimile of a fragmentary portion of the multi-column record material used in the present machine, showing the items composing each transaction printed in various ones of the different columns according to the different classifications of the item and the sub-total or total of each transaction printed in a certain one of said columns.

Fig. 3 is a facsimile of another fragmentary portion of the record material, showing a recapitulation of the cash items previously printed in each of the different columns, and the total of the cash items in each column or different classification printed in a certain one of said columns.

2

Fig. 4 is a facsimile of still another fragmentary portion of the record material, illustrating the use of the machine as an adding machine for obtaining and printing the grand total of the various items.

Fig. 5 is a cross-sectional view of the machine taken just to the right of the ten-cent amount keybank, showing said amount keybank, the differential mechanism associated therewith, and also showing the indicators, the printing mechanism and the totalizer mechanism actuated by said differential mechanism.

Fig. 6 is a detail side view of the bank of transaction keys and the differential mechanism associated therewith.

Fig. 7 is a detail side view of the list key in the bank of transaction keys, showing the various detents associated therewith and in particular the special detent for holding said key depressed until the total of a transaction is printed.

Fig. 25 is a detail side elevation of certain control means to be used when charge items are to be entered into the group totalizer.

GENERAL DESCRIPTION

The machine disclosed in the aforesaid Carey et al. application is provided with a single totalizer which is used when the machine is operated both as a cash register and as an adding machine. When such machine is used as a cash register, a total or sub-total operation can be performed only after a control slide has been manually adjusted to properly condition the machine for performing such operations. On the other hand, when the control slide has been adjusted to condition the machine for use as an adding machine, a sub-total or total operation may be performed by the simple depression of certain control keys provided for that purpose. When the machine of the Carey et al. application is used as a cash register, it is not practical to obtain a total of the items comprised in each multiple item transaction registered, due to the manual adjustment which must be given to the control slide in order to accomplish such results. The machine is therefore more suitably adapted, when used as a cash register, to accumulate all of the items comprising the various transactions registered in the machine, thus maintaining a running total of all the items entered into the machine. However, if it is desired to change the operation of the machine from that of a cash register to that of an adding machine, it is first necessary to reset the totalizer to zero to clear the running total therefrom before the machine can be used as an adding machine.

The present machine is provided with two totalizers, namely, an item totalizer and a group totalizer, with novel selecting means for controlling the shifting of the different totalizers preparatory to engaging them with the amount actuators, and with novel means for controlling the engagement and disengagement of the totalizers and the actuators. The present arrangement provides a plurality of depressible control keys, certain of which control the operation of the item totalizer when the machine is used as a cash register, so that the various items comprised in each transaction may be entered thereon, a sub-total printed therefrom, the amount of taxes or other amounts then added thereon, and the total cleared therefrom printed on the record material, and transferred to the group totalizer. If the transaction to be entered into the machine involves only a single item, then the group totalizer will be selected by other of said control keys

to receive said item. Before the machine can be used as an adding machine, it is necessary to operate the machine under control of one of the control keys in order to remove any amount standing on the item totalizer, which amount is automatically transferred to the group totalizer to insure that a running total of all the items will be retained in the machine. A manually adjustable control slide is provided for conditioning the machine to perform various functions, such as, for example, those of an adding machine, when only the item totalizer is utilized. When the machine is being used as an adding machine, a sub-total or grand total may be printed of the amount standing on said item totalizer at any time by simply depressing either the subtotal or total control key, just as is done when the machine is being operated as a cash register; however, under these conditions the amount cleared from the item totalizer is not transferred to the group totalizer. It will be evident from the above that when changing the use of the machine from a cash register to an adding machine, the total of the amounts registered therein during its use as a cash register remains on the group totalizer. When it is desired to again use the machine as a cash register it is relatively simple to clear the item totalizer and adjust the control slide to condition the machine for use as a cash register.

The machine of this invention is arranged to be normally operated by electrical means; however, manual means is provided for operating the machine when necessary or desirable.

As presently constructed, the machine embodying this invention has five rows of adding or amount keys, four rows of ledger or number printing keys, one row of transaction keys, and one row of column selection keys.

The functioning of the machine either as a cash register or as an adding machine is controlled by a control slide conveniently located on the lefthand side of the keyboard. The control slide has five positions of adjustment; namely, Register, Lock Register, Read Total, Adding, and Reset Total and is provided with a lock which may be operated by two types of keys, either of which may be used to lock the control slide in either Register position or Lock Register position. One type of key permits the control slide to be moved to the Reset Total position and is known as the Reset key. The other type of key, which is known as the Read key, does not permit the control slide to be moved beyond the Read Total position. When the control slide is in Register position, the machine is conditioned to function as a cash register, and when said control slide is in Adding position the machine is conditioned to function as an adding machine.

In the art, a total recording operation is often referred to as a "reset" total operation and a sub-total recording operation is often referred to as a "read" total operation. Therefore the terms "total" and "reset" total as used herein refer to an operation in which the totalizer is cleared of the amount standing thereon and the terms "sub-total" or "read" total refer to operations in which the amount remains on the totalizer.

When the machine is used as a cash register, the fifth or highest order row of amount keys is locked against depression, and only the four lower order rows of amount keys may be used for registering amounts, thus providing a maximum registering capacity of \$99.99. When the machine is used as an adding machine, the fifth row of

amount keys is unlocked, thus giving the keyboard a capacity of \$999.99. This change in keyboard capacity is controlled by the control slide, and when said slide is in any other position except Adding position, the fifth row of amount keys is locked against depression.

The control slide, in addition to controlling the functions of the machine as a cash register or adding machine, also controls the engaging and disengaging of the group totalizer and the item totalizer with and from the actuators, each of which totalizers has a wheel for each of the five denominational orders of the amount banks and a sixth order wheel which is used to receive overflow amounts from the wheel in the highest or fifth denominational order. When the control slide is in Register position, the bank of transaction keys functions in conjunction therewith to control the selection of the totalizers for engagement with or disengagement from the amount actuators. For example, when the machine is conditioned for operation as a cash register, the Cash key and the Received-on-Account key, each controls the selection of the group totalizer. If a multiple-item cash transaction is to be entered into the machine, the List key is utilized to select the item totalizer. When the List key is depressed, means is provided for maintaining it in depressed position until either the Total Cash List or the Total Charge List key is depressed. The Total Cash List key controls the selection, together with the selective engagement and disengagement of both totalizers and the actuators, in such a manner that the amount on the item totalizer will be removed therefrom and transferred to the group totalizer during a single operation of the machine. If it is desired to print and indicate the sub-total of said multiple-item transaction, then the Sub-Total key is depressed, which controls the selection of the item totalizer in order to read the same. Any additional amounts such as the amount of tax involved in said transaction may then be set up on the amount keys and added into the item totalizer. The Total Cash List key is then depressed to clear the total from the item totalizer and transfer the same to the group totalizer, and at the same time this key controls means for printing this total on the record material.

The Paid-Out and No-Sale keys do not effect selection of any of the totalizers and merely serve to control the adjustment of means for indicating and printing the amounts, together with identifying symbols.

In the case of a charge transaction, the Charge key is depressed to enter a single-item transaction, and said key merely controls means for indicating and printing the amounts, without selecting any totalizers. On the other hand, if a multiple-item charge transaction is to be entered into the machine, the List key is depressed and the various items constituting such transaction are entered into the machine. The List key will control the selection of the item totalizer for adding such items thereon. The Total Charge List key is then depressed to cause the total to be cleared from the item totalizer without transferring such amount to the group totalizer and to control means for indicating and printing said total charge amount, together with an identifying symbol.

If it is desired to have the machine accumulate charge items on the group totalizer in the same manner as is done with respect to cash items, a single member may be provided which

can be easily placed in the machine to enable the machine to accomplish this result.

When the control slide is in Lock Register position, all of the keys on the keyboard are locked against depression and the machine is locked against release for operation.

When the control slide is in Read Total position, operation of the machine causes the group totalizer to be read automatically.

- 10 If the control slide is in the Adding position, the machine functions as an adding machine, and in this case the item totalizer is engaged with and disengaged from the actuators. The fifth or highest order row of adding or amount keys is released for depression. When it is desired to read or take a sub-total from the item totalizer, the Sub-Total key is depressed. The Total Cash List key is depressed to clear the total amount from the item totalizer, but in this case such amount is not transferred to the group totalizer as is done when the machine is operated as a cash register, as previously described.

When the control slide is moved to the Reset Total position, operation of the machine causes the group totalizer to be cleared and the amount removed therefrom, such amount being set up on the indicators and printed on the record material.

It will be seen from the above that the control exercised by the Total Cash List key over the engagement and disengagement of the item and group totalizers varies according to the position of the control slide.

The differential mechanisms for the five rows 35 of adding or amount keys, in addition to controlling the positioning the corresponding totalizer wheels, also control the positioning of corresponding type wheels for printing records upon record material. Also, the differential mechanisms for the four lower order rows of amount keys control the positioning of corresponding indicator wheels, which are visible through apertures in the front and back of the upper portion 40 of the machine cabinet, for indicating amounts when the machine is used as a cash register. The type wheels for the four lower order rows of amount keys are mounted in a framework which is shiftable laterally from normal printing position to any one of eight columnar printing positions for the classifying of items when the machine is used as a cash register. The columnar positioning of the framework for the four lower order amount type wheels is controlled by the row of column selecting keys, 45 which row is located on the righthand side of the keyboard. The transaction keys control the positioning of corresponding indicators and corresponding type wheels for indicating and recording the type of transaction being performed.

The record material, a fragmentary portion of which is shown in Fig. 2, is comparatively wide, and is divided into nine vertical columns, the extreme lefthand column being considerably wider than the other eight columns, and is used for the printing of the ledger numbers and all other identifying data, amounts, and is also used for the autographic entering of additional information opposite the printed entries. When the machine is used as a cash register, all sub-totals and totals are printed in this wide lefthand column, and when the machine is used as an adding machine, all amounts, sub-totals and totals are printed in this lefthand column.

When the machine is used as a cash register,

no-sale items are invariably printed in the left-hand column, but cash and charge items cannot be printed in the lefthand column, and therefore must be printed in one of the other eight columnar positions, located to the right thereof. When the machine is used as a cash register, received-on-account and paid-out items may be printed in the lefthand column, or in any desired one of the other eight columns of the record material.

DETAILED DESCRIPTION

Machine framework

The mechanism of the machine is supported by two main frames 60 and 61 (Figs. 5, 6, 8 and 22) secured to a machine base 62. The indicator mechanism and a part of the printer positioning mechanism are supported by auxiliary frames 63 and 64 (Figs. 5, 14, 18 and 22) secured, respectively, to the main frames 60 and 61. The machine base 62 is supported by a drawer cabinet (not shown here but illustrated in the above Carey et al. application) which encloses a cash drawer. The mechanism of the machine is enclosed in a suitable cabinet 65.

Referring to Figs. 1 and 9, a control slide 72 is slidably mounted on the left main frame 60 in a manner to be described later, and said control slide 72 supports a lock having a rotary locking bolt 73 with a locking lug thereon adapted to engage notches in a locking plate, when said bolt is rotated by a key which may be inserted into said lock. The locking plate just referred to is not shown herein, but is illustrated and described in Fig. 29 of the above mentioned Carey et al. application. The notches in the locking plate are so arranged as to correspond to the Register position and the Lock Register position of the slide 72, so that said slide may be locked in either of these positions by the possessor of the key to the lock in said slide.

Operating mechanism

Under normal conditions, a conventional type of electric motor drives a main shaft 79 one clockwise revolution during each machine operation. However, a hand crank, such as that shown in the above mentioned Carey et al. application, is provided for driving said main shaft when necessary or desirable.

Keyboard

Referring to Fig. 1, the keyboard of the present machine comprises four rows of amount keys 80, giving a maximum registering capacity of \$99.99; an additional row of amount keys 81, used in conjunction with the amount keys 80 to increase the keyboard capacity to \$999.99 when the machine is used as an adding machine; four rows of number printing control keys 82, for controlling the printing of identifying numbers; and one row of transaction keys 83 for controlling the positioning of the corresponding printing wheels to record the type of transaction being performed and also for controlling the engagement and disengagement of the totalizer with and from the actuators and also for controlling the shifting of the totalizers to effect the proper selection thereof. The keyboard also comprises a row of column selecting keys 84 for selectively controlling the shifting of the four amount type wheels corresponding to the four rows of amount keys 80, to cause various items to be printed in corresponding columns of the record material; a space key 85 for manually line-

spacing the record material; and a drawer release key 86 for manually releasing the cash drawer. A motor bar 87 is provided for initiating machine operation; while the control slide 72 is used to control the functions of the machine.

The keys 80 to 86 inclusive, are not assembled in individual banks, as is the usual custom, but instead, all of said keys are assembled in a single unit keyboard framework comprising front and back frames 88 and 89, one at each end of the framework (Figs. 5, 6 and 8), a partition plate 90 for each row of keys, an upper support plate 91, and a lower support plate 92. All of the above plates are secured together by means of tenon and slot connections, not shown herein. Small rods 93 pass through holes in the partition plates 90 and slots in the keys 80 to retain the latter in the machine. The keyboard assembly is retained in place in the machine by means of four screws 94, only one of which is shown herein, which pass through clearance holes in bent-over ears on the front and back frames 88 and 89, and are threaded into holes in the main frames 60 and 61. All that is necessary to remove the entire keyboard assembly from the machine is to remove the four screws 94.

A keyboard top plate 95 (Figs. 1, 5, 6 and 8) is provided for covering the keyboard framework and for giving a finished appearance to the keyboard assembly. The keyboard top plate 95 has provided therein clearance openings for clearing the tips of all of the keys of the keyboard and, in addition, has openings for the control slide 72 and the motor bar 87.

Amount keys

Inasmuch as the mechanism associated with the keys is substantially duplicated for each row of amount keys, it is believed that a description of the ten-cent denominational amount keys, shown in Fig. 5, will suffice for all.

The keys 80 (Figs. 1 and 5) for the ten-cent amount bank are depressedly supported in slots in the plates 91 and 92 and are retained against removal by means of slots therein, through which slots extend corresponding ones of the tie rods 93. Each of the amount keys 80 is normally retained in undepressed position by coil spring 101, which extends horizontally through the entire keyboard assembly, there being one such spring for all keys of like numerical value, each spring being engageable by notches in the keys of like value in all the different banks of keys. The springs 101 rest on the top surface of the upper support plate 91; when a key is depressed, said spring is tensioned by being forced downwardly through an opening in said plate, adjacent the key stem; and, when said key is released, the spring 101 returns it upwardly to its undepressed position, as here shown.

This type of keyboard spring construction is fully disclosed in the above mentioned Carey et al. application and is similar to the construction shown in United States Patent No. 2,210,099, issued August 6, 1940, to B. M. Shipley, to which reference may be had for a more detailed description of the keyboard spring construction.

Each of the rows of amount keys has a detent 102 (Fig. 5) for locking the keys in depressed position, and a control plate 103 for releasing the zero stop pawls so that the differential mechanism may be moved away from zero position and be arrested by the depressed amount keys. The detent 102 and control plate 103 are substantially like and operate in the same manner as the de-

tent 206 and plate 207 illustrated in Fig. 31 of the before mentioned Carey et al. application. The detent and control plate and their operation are fully described in the Carey et al. application and reference may be had thereto for a full understanding thereof. The amount keybanks are of "flexible" construction, wherein the depression of a key in the keybank releases a previously depressed key in the same keybank.

Amount differential mechanism

Since the construction and operation of the differential mechanism associated with each bank of amount keys is substantially the same as that illustrated and described in the above mentioned Carey et al. application, it is felt that a very brief description thereof will suffice herein.

Each bank of amount keys 80 or 81 has associated therewith one of a plurality of differential slides 104 (Fig. 5) shiftably supported in a framework comprising front and back members 105 and 106 secured, respectively, to inverted U-shaped bars 107 and 108, in turn secured to partition plates 109 for each order (only one here shown) said plate in turn being mounted on rods 110 and 111 supported by the main frames 60 and 61. Each differential slide 104 has formed thereon four upward projections having ears 112 bent toward the left, said ears being adapted to cooperate with the odd numbered keys 1, 3, 5 and 7, and said slide likewise has four similar projections having ears 113 thereon bent toward the right and arranged to cooperate with the even numbered keys 2, 4, 6 and 8. The stems of the amount keys in each bank are arranged in staggered formation so that the stems of the odd numbered keys are arranged toward the left while the stems of the even numbered keys are to the right.

Depression of any one of the amount keys except the "9" key moves the stem thereof into the path of the corresponding ear 112 or 113 and simultaneously moves the zero stop pawl out of the path of another ear (not shown herein) on said slide 104, as is fully illustrated and described in the above mentioned Carey et al. application. Rearward movement of the differential slide 104, under influence of the amount differential mechanism, to be later described, causes the ear 112 or 113 to engage the lower end of the stem of the depressed amount key to arrest the slide 104 and the corresponding differential mechanism after differential movement corresponding to the value of the depressed amount key. When the "9" key in any amount bank is depressed, the slide 104 travels the full distance rearwardly to the "9" position, which is determined by a projection 114 thereon coming into contact with a square stud 115 in the lefthand partition plate 109 for that particular denomination.

The slide 104 (Fig. 5) is connected to and controls the extent of movement of a corresponding differential mechanism to different positions in accordance with the control exerted by the keys during the rearward movement of the slide. In adding operations the corresponding wheel of the selected totalizer is engaged with said differential mechanism after the differential mechanism has been differentially positioned, and return movement of the differential mechanism to its home position adjusts said totalizer wheel in accordance with the value of the depressed amount key.

The amount differential mechanism which is shown in Fig. 5, includes a differentially movable actuator 123, free on a rod 124, and having a stud

122 engaging a slot in an arm 121 secured to the differential slide 104, whereby the actuator can drive the slide 104 in unison therewith and the slide can control the extent of movement of the actuator 123.

During each cycle of operation of the machine, the actuator 123 is driven first in a clockwise direction and then in a counter-clockwise direction by a driving segment 134, also loosely mounted on rod 124, which driving segment is given its clockwise and counter-clockwise movement during each operation of the machine, by means herein-after to be described.

The actuator 123 is connected to the driving segment 134 by means of a latch 127 pivotally mounted on stud 128 on a latch plate 129 also loose on rod 124. A stud 126 on the latch 127 works in an inclined slot 125 formed in the actuator 123 and also in a slot 130 formed in a latch control plate 131, and provides the means whereby these parts are connected for joint movement. A spring 132 urges the actuator 123 clockwise and the latch control plate 131 counter-clockwise, creating a scissors action between the slots 125 and 130 and the stud 126 to retain the latch 127 normally in clockwise position as shown in Fig. 5, in which position the latch engages a shoulder 133 on the driving segment 134. As long as the latch 127 remains engaged with the shoulder 133, the driving segment 134, during its clockwise movement, can move the actuator 123, the latch control plate 131 and the differential slide 104.

As explained earlier herein, the differential slide 104 may be arrested under control of the amount keys after different extents of movement have been imparted to the slide. When the slide 104 is thus arrested, it is effective, through the arm 121 and stud 122, to arrest further movement of the actuator 123. However, at this time the latch 127 will continue to move, and this further movement will enable the stud 126 on the latch 127 to coat with the slot 125 in the actuator 123 to cam the latch 127 out of engagement with the shoulder 133 on the driving segment 134 and release the actuator 123 from its driving means. In this manner, the differential slide 104 is effective to control the differential movement of the actuator 123 according to the amount set up on the amount keys.

During the counter-clockwise movement of the driving segment 134, a stud 173 thereon engages an extension on the latch plate 129, which extension is not shown in Fig. 5, but is similar to the extension 252 shown in Fig. 6, and drives the latch plate 129, the latch 127, and, through the stud 126, drives the differential actuator 123, the latch control plate 131, and the differential slide 104 back to normal or starting position.

The means for imparting the above mentioned clockwise and counter-clockwise movements to the driving segment 134 during each operation of the machine will now be described.

As previously explained, the main shaft 79 makes one complete clockwise revolution during a machine operation. The driving segment 134 has therein a slot 141 (Fig. 5) which engages a stud (not shown herein but corresponding to the stud 245 in Fig. 8 of the above mentioned Carey et al. application) in a differential drive arm 142 free on a rod 143 supported by the frames 60 and 61. An eccentric 144 adjustably connects the arm 142 to a companion arm 145, also free on the rod 143, and said arm 145, and similar arms for the other differential mechanism are connected

together by a rod 146 which is carried by a differential cam lever 147 also free on the rod 143. The cam lever 147 carries rollers 148 and 149 which cooperate, respectively, with the peripheries of companion plate cams 150 and 151 secured to the main shaft 79. The lever 147 is located on the lefthand end of the rod 143 and supports the lefthand end of the rod 146, while a similar cam lever (not shown) is located near the righthand end of said rod 143 and supports the righthand end of said rod 146, and carries rollers which cooperate with a pair of companion plate cams, not shown but like the cams 150 and 151, also secured to the main drive shaft 79. The rod 146, therefore, forms an operating connection between the cam levers, as 147, and the arms 145 for the amount differential mechanism and the differential mechanism associated with the number printing control keys 82.

As previously explained, the main shaft 79 (Fig. 5) makes one clockwise revolution during a machine operation. When the machine is in home position, the slide 104 and the actuator 123 have been moved one position beyond zero, as here shown, for the purpose of enabling transfers to be effected, as fully explained in the above mentioned Carey et al. application. At the beginning of a machine operation, the cams 150 and 151, as well as the other pair of cams (not shown) corresponding thereto, through the connections here shown, rock the arm 142 and driving segment 134 a short distance clockwise to move the actuator 123 and slide 104 to zero position where they remain during a period in which the restoration of any tripped transfer mechanism takes place in a manner fully explained in the Carey et al. application. After the transfer mechanism has been restored, the cams 150 and 151 impart further clockwise motion to the driving segment 134 which tends to drive the actuator 123 and differential slide 104 further. If no amount key in the bank has been depressed, further movement of the slide and the actuator will be prevented by the zero stop pawl, but if an amount key has been depressed, the slide 104 and the actuator can continue their movement until one of the bent-over ears 112 or 113 on the slide 104 comes into contact with the lower end of the stem of the depressed amount key. This obstructs further movement rearwardly of the slide 104 and the actuator 123 in accordance with the value of the depressed amount key. Stopping the actuator 123 causes the stud 126 to ride up the inclined surface of the slot 125, against the action of the slot 130 and the spring 132, to disengage the latch 127 from the shoulder 133 of the driving segment 134 in a position corresponding to the amount key 80 which has been depressed. After the latch 127 has been disengaged from the driving segment 134, the segment 134 is free to complete its clockwise movement.

Since the operation of the transfer mechanism to effect a transfer and the manner in which it is restored form no part of the present invention and are fully illustrated and described in the before mentioned Carey et al. application, reference may be had to that application for a full understanding thereof.

One end of a beam 157 (Fig. 5) is pivotally connected to the latch plate 129, and, when the arm 142 nears the terminus of its initial clockwise movement, a roller 158, carried thereby, engages an arcuate surface on the forward edge of said beam and forces a curved surface on the inside edge thereof into engagement with the periphery

of a hub 159, free on the rod 124, to position said beam 157 in accordance with the value of the depressed amount key 80. The differential positioning of the beam 157 is transmitted through a link 160 to the indicator mechanism and the printing mechanism by means fully illustrated and described in the above mentioned Carey et al. application, and reference is hereby made thereto for a full understanding thereof.

- 10 After the differential actuator 123 (Fig. 5) has been positioned under the influence of the depressed key 80 during amount entering operations, either one of two totalizer wheels 170 and 171, (Figs. 5, 19 and 22) for this particular denomination, depending upon which one of two totalizers is selected, is engaged with a plurality of gear teeth 172 in said actuator 123. Return movement counter-clockwise of the differential drive arm 142 under the influence of the cams 150 and 151, turns the driving segment 134 in a counter-clockwise direction, causing the stud 173 thereon to engage the extension of the latch plate 129, not shown but similar to extension 252 shown in Fig. 6, at the same time that the shoulder 133 or undercut portion of the periphery of the segment 134 is moved past the latch portion of the latch 127. When the undercut portion of the periphery of the segment 134 moves opposite the latch 127, the camming action of the angular slots 125 and 130 in the actuator 123 and the plate 131, under the influence of the spring 132, immediately reengages said latch with the shoulder 133 on the segment 134. The latch plate 129 and the latch 127 are now free to return counter-clockwise in unison with the segment 134 and, through the stud 126, carry the latch control plate 131 and the actuator 123 counter-clockwise in unison therewith from set position to home position. The return counter-clockwise movement of the actuator 123 causes the teeth 172 to rotate the totalizer wheel engaged therewith for this particular denomination in a clockwise direction, in accordance with the value of the depressed amount key 80, to add in said wheel said value.
- 15 After the actuator 123 has been returned to home position, the totalizer wheel is disengaged therefrom.

- 25
- 30
- 35
- 40
- 45

In total and sub-total recording operations the selected totalizer wheel 170 or 171 is engaged with the teeth 172 before the actuator 123 moves clockwise from its home position. The clockwise movement of the actuator 123 rotates the engaged wheel counter-clockwise to its zero position where the wheel will be effective to prevent further movement of the actuator in a well known manner fully explained in the above mentioned Carey et al. application. After the actuator has completed its clockwise movement, the totalizer wheel is disengaged therefrom.

In sub-total recording operations, the totalizer wheel is reengaged with the actuator before it begins its return movement counter-clockwise and enables the amount removed from the wheel to be restored. After the actuator has been restored to its home position the totalizer wheel is disengaged therefrom.

The mechanism for engaging and disengaging the wheel with and from the actuator in these different kinds of operations will be described more fully hereinafter.

Transaction keys

The transaction keys 83 (Figs. 1, 6 and 7) are depressibly supported in the keyboard framework in the same manner as the amount keys previously

described. The transaction key bank contains the following keys (Fig. 1) Total Charge List, Total Cash List, Sub Total, List, No Sale, Paid Out, Received on Account, Charge and Cash, which keys have been numbered respectively from 1 through 9 according to their position in the bank, in order that the controls exerted by the different keys may be more readily explained.

Depression of any one of the transaction keys 83 causes a projection 231 on the forward or left side of the key stem to cooperate in the forward edge of a corresponding slot in a locking detent 225 to shift the detent forwardly, or toward the left, as here viewed, against the action of a spring (not shown) until the projection passes beneath the detent. When this occurs, the detent 225 is returned by the spring to a position over the projection 231 to lock the key in depressed position. This keybank is of the "flexible" type and any key, except the List key, may be released by the depression of another key in the bank.

The machine is provided with the usual keylock shaft 286 which is released for clockwise movement to initiate an operation of the machine, and is given a counter-clockwise movement near the end of each machine operation. As is well known, and is shown fully in the above mentioned Carey et al. application, a series of key releasing members are loosely mounted on the keylock shaft and are operated counter-clockwise by a bail 230 of a yoke loose on shaft 286 but driven by the shaft near the end of each machine operation to shift the locking detents for the various keybanks to the left to release any depressed keys. One of these releasing members, shown at 229 in Figs. 6, 23 and 24, is provided to shift the detent 225 forwardly or to the left to release any depressed key in this bank except the List key.

A further locking detent 226, Figs. 6 and 7, has an extension 372 on its right end carrying a stud 371 which engages a notch in a member 353 loose on keylock shaft 286, and is urged toward the left by a spring 354 which engages the member 353. This detent 226 has slots arranged therein so that it is only operated by the List key. A projection 232 on the rear or right hand side of the key stem of the List key cooperates with the associated slot in detent 226 to shift the detent rearwardly against the action of the spring 354, and when the key has been depressed the detent will return forwardly to engage over the projection 232 and retain the List key in depressed position until the detent 226 is shifted under control of the Total Cash List key or Total Charge List key in a manner to be described. The detent 226 therefore serves to retain the List key in depressed position throughout the entry of the several items which make up a multiple-item transaction even though the locking detent 225 will be operated near the end of each item-entering operation.

As fully explained in the above mentioned Carey et al. application, the various total and sub-total keys and the No Sale key operate a control plate 233 to lock the amount keys against depression and all keys except the Charge and Cash keys are effective, through extensions 234 of a control plate 235 in the bank of column selecting keys 84, to withdraw the hook 236 (Fig. 8), from a member 237 secured to the keylock shaft 286. The instant machine is provided with a further hook 227 (Fig. 6), which cooperates with another member 228 secured to the keylock shaft 286. A control plate 259 in the transaction keybank is shifted to the left by the depression of any transaction key and is effective to remove this hook 227 and also re-

move the zero stop pawl 257 from the differential slide for this bank.

The control over the removal of the hooks 227 and 236 is such that the depression of any key in the transaction bank except the Charge and Cash key will remove both hooks to allow the keylock line to be released by the Motor Bar, but when the Charge and Cash keys are depressed, they will only be effective to remove hook 227, and will require the depression of a key 84 in the column selecting bank to remove hook 236 so that the keylock line can be released by the Motor Bar.

As stated earlier herein, detent 225 is shifted forwardly near the end of each machine operation and will release any key, except the List key, which may have been depressed. Even though detent 225 is operated, the List key will be retained in its depressed position by the locking detent 226 until the detent 226 is shifted rearwardly or toward the right. The mechanism for shifting the detent 226 to the right will now be described.

As shown in Figs. 5, 6, 7, 23 and 24, the releasing members 215 and 216 for the ten-cent and units denominational orders are loosely mounted on the keylock shaft 286 and are connected together by a sleeve. These releasing members 215 and 216 have extensions on their lower ends, in which extensions are slots as 329, one of which is shown clearly in Fig. 5, and these slots have a lower narrow portion and an upper wider portion. Also mounted on the keylock shaft 286 is a lever 327 which has a slot 330 in its lower end. A rod 328 extends through the slots in the extensions of the release members 215 and 216 and also through the slot 330 in the lever 327. If the rod 328 is in the lower or narrow portions of the slots 329 in the release members 215 and 216, it will be driven thereby when they are rocked counter-clockwise and will impart this movement to the lever 327. On the other hand, if the rod 328 is in the upper or wider portions of the slots in the release members 215 and 216 the rod 328 will not be driven thereby and the lever 327 will not be rocked.

When lever 327 is rocked counter-clockwise, an upward extension thereof will contact a stud 339 in an arm 340, loose on a shaft 351 supported by the main frames 60 and 61, and will rock the arm counter-clockwise. The arm 340 is connected by a sleeve to another arm 341, which is also loose on shaft 351. A stud 342 carried by arm 341 engages a slot 352 in the member 353 loose on the keylock shaft and when the lever 327 rocks the arms 340 and 341 counter-clockwise, arm 341 will rock the member 353 clockwise and, through the stud 371, will shift the locking detent 226 to the right at the same time the locking detent 225 is shifted to release the List key.

The rod 328 is carried by links 325 which are pivoted on arms 324 fast to a shaft 331, journaled in a pair of totalizer supporting plates 184 (Figs. 12 and 22) which are fastened to the main frames 60 and 61. Shaft 331 normally occupies a position as shown in Fig. 24 in which the rod 328 is located in the lower or narrow portions of the slots 329 in the extensions of the arms 215 and 216. However, in any operation in which the List key is depressed, shaft 331 will be rocked counter-clockwise by means later to be described, and when so rocked will carry the rod 328 into the upper or wide portions of the slots to prevent the operation of the lever 327 and the shifting of the locking detent 226. Shaft 331 will remain in its shifted position until an operation in which either the Total Cash List or Total Charge List

key has been depressed, and during this operation the shaft 331 will be rocked clockwise to return the rod 328 to the lower portion of the slots to enable the locking detent 226 to be shifted to release the List key.

A control detent 292 is shiftable forwardly by the control slide 72 in a manner to be described, and is effective to lock all the transaction keys except the Total Charge List, the Total Cash List and Sub-Total keys against depression when the control slide is in any position except Register position.

Each of the transactions keys 83, when in depressed position, is effective to control the differential positioning of the related transaction differential mechanism.

Transaction differential mechanism

The differential mechanism which is controlled by the transaction keys 83 is shown in Fig. 6. This mechanism is similar to and operates in exactly the same manner as the differential mechanism for the amount bank shown in Fig. 5 and explained earlier herein, with the exception that the tens transfer mechanism and actuating teeth are omitted from the differential segment in the transaction differential, which segment corresponds to the actuator in the amount differential mechanism. A latch 246 carried by a latch plate 245 engages a shoulder on a driving segment 244 and enables the latch plate 245 to be driven thereby. A stud 247 in the latch 246 extends through angular slots in a differential balance plate 248 and a differential segment 249 to operatively connect these parts to the latch plate 245. The differential segment 249 carries a stud engaged by the bifurcated lower end of a plate 250 (shown broken away herein) secured to the transaction differential slide 251 slidably mounted in the differential slide framework in exactly the same manner as the differential slide 104 (Fig. 5) for the ten-cent amount bank previously described.

The transaction differential slide 251 is normally retained in zero position by the zero stop pawl 257 free on a shaft 258 journaled in the frames 60 and 61. However, as explained earlier herein, depression of any one of the transaction keys 83 (Fig. 6) shifts the control plate 259 forwardly to rock the zero stop pawl 257 to ineffective position. At the same time, the lower end of the stem of the depressed key is moved in the path of the corresponding one of a series of bent-over ears on the slide 251. The differential driving segment 244 is connected to an arm 260 free on the rod 143, said arm being connected by an adjustable eccentric to a cam lever 261 also free on the rod 143. The cam lever 261 carries rollers 262 and 263 which cooperate, respectively, with the peripheries of companion plate cams 264 and 265 secured to the shaft 79.

Clockwise rotation of the shaft 79 (Fig. 6) causes the cams 264 and 265 to rock the lever 261 and the arm 260, first in a clockwise direction, to rock the transaction differential mechanism clockwise to shift the slide 251 rearwardly until such rearward movement is interrupted by the depressed transaction key 83. This releases the latch 246 from the driving segment 244 and positions the slide 251 and the differential segment 249, the balance plate 248 and the latch plate 245 in accordance with the depressed transaction key 83. As the arm 260 nears the terminus of its movement clockwise, it causes a roller 266, carried thereby, to engage an arcuate surface on a beam

243 which is pivoted on the latch plate 245. The roller 266 forces said beam into contact with a bushing on the rod 124 to position said beam in accordance with the depressed transaction key 83.

5 A link 242 connects the beam 243 to a bell crank 240 (Fig. 15) which is free on shaft 241 and which is connected by link 239 to an arm 238 fastened to shaft 221 and enables the differential movement of the beam 243 to be utilized to position 10 shaft 221.

Shaft 221 has a control segment 219 (Figs. 14 and 21) fastened thereon for differential movement therewith under control of the transaction keys. A second control segment 220 is pivoted on

15 a stud 222 on an extension 223 of the auxiliary frame 64 and is connected by a link 224 to the segment 219 so that when segment 219 is differentially moved in either direction by the shaft 221, the control segment 220 will be given a like extent of movement in the same direction. Control segment 219 has certain means thereon for controlling a totalizer selecting mechanism and other means which are effective with the control segment 220 to control a totalizer engaging means.

20 The control surfaces of the segments 219 and 220 have been given numbers corresponding to those given to the transaction keys to show which portions thereof will be moved to controlling position when the corresponding transaction key 25 has been depressed. Fastened to the control segment 220 by stud 364 is a control segment 363 (Fig. 18) which is positioned in the same manner as the control segment 220 and is effective to control the totalizer selecting mechanism. The manner in which the segments exert their control on 30 the totalizer engaging and selecting mechanisms will be explained more fully hereinafter.

25 The positioning of the shaft 221, under the influence of the transaction keys 83, is transmitted, by means shown and described in the aforesaid Carey et al. application, to the indicating mechanism, to impart to the latter the proper adjustment for indicating the type of transaction being registered. For a full understanding of 35 this mechanism, reference is hereby made to said Carey et al. application.

Control slide

40 As previously mentioned, the manually adjustable control slide 72 (Fig. 1) is provided for conditioning the machine to perform different functions. For example, when the slide 72 is moved to its Register position (Fig. 9), the machine is thereby conditioned to function as a cash register.

45 The cash register, in this instance, involves the use of both the item totalizer and the group totalizer. The item totalizer serves to accumulate the items of a multiple item transaction before transferring the total thereof to the group totalizer.

50 The transaction "Total Cash List" key 83 controls means for resetting the item totalizer to zero and transferring the amount removed therefrom to the group totalizer during one operation of the machine. To read or obtain a sub-total of the items accumulated on the item totalizer, the transaction "Sub-Total" key 83 is depressed.

55 Single-item transactions however are entered directly onto the group totalizer which accumulates a running total of the various cash transactions entered into the machine.

60 The slide 72 is adjustable to either its "Read Total" position or its "Reset Total" position to control the reading or resetting of the group totalizer.

When the control slide 72 is moved to its Locked Register position, it locks the machine against operation.

When it is desired to use the machine as an adding machine, the control slide 72 is moved to its Adding position. When the machine is thus conditioned to function as an adding machine, the item totalizer is made available for use. With the control slide 72 in Adding position, the fifth order amount keys 81 are released for operation to increase the keyboard capacity of the machine. The "Total Cash List" key 83, in this instance, is adapted to control the resetting of the item totalizer to zero without effecting a transfer of the amount taken therefrom to the group totalizer, as is done when the machine is being used as a cash register. The "Sub-Total" key 83 is employed to read or obtain a sub-total of the amounts entered on the item totalizer.

When the machine is used as a cash register the various items of multiple-item charge transactions can be accumulated in the item totalizer in the same manner as a multiple-item cash transaction. However, these Charge items are not accumulated on the group totalizer which normally serves to record only cash items. The "Total Charge List" key 83 is depressed when it is desired to obtain the total of said multiple item charge transaction from the item totalizer, and this key causes the resetting of the item totalizer without such amount being transferred to the group totalizer. A single-item charge transaction is not accumulated on the item totalizer, but is merely printed and indicated.

A simple device is provided which may be quickly and easily installed in the machine for adapting it to handle charge items in the same manner as it does cash items, which means will be fully described hereinafter.

The control slide 72 (Fig. 9) is shiftably mounted by means of parallel slots therein cooperating with studs 277 and 278 secured in the left frame 60. The slide 72 has therein a series of notches 279 corresponding to the various positions of adjustment of said slide, which notches cooperate with a stud 280 in a spring-pulled arm 281, free on a stud 282 secured in a frame 60, to locate said slide in its various positions of adjustment. As the stud 280 rides from one notch 279 to another, the arm 281 is rocked counter-clockwise, against the tension of a spring, to momentarily raise a projecting finger 283 on said arm into the path of a shoulder 284 on an arm 285, secured on the lefthand end of the keylock shaft 286, journaled in the frames 60 and 61, to obstruct clockwise releasing movement of said shaft when the control slide 72 is being moved from one position to another, as is fully shown and described in the before mentioned Carey et al. application. When the control slide 72 is moved to "Lock Register" position, a stud 287 (Fig. 9) carried thereby, moves over a projecting finger 288 of the arm 285 to lock the keylock shaft 286 against releasing movement, thereby preventing operation of the machine. In a manner similar to that shown in the Carey et al. application, a cam slot 289 in the control slide 72 cooperates with a stud on an arm 290 secured to a shaft 258 journaled in the frames 60 and 61 and is effective to rock the shaft 258 to cause an arm 291 thereon (Fig. 6) to shift the control detent 292 forward when the control slide 72 is in all positions except Register position. Control detent 292 is sufficiently wide at its rear end to engage the control plates 259 and 235 to shift them forwardly to move both hooks

227 and 236 to releasing position so that the machine may be released for operation without requiring the depression of a transaction key 83 or a column selecting key 84. The control slide 72 is also effective, through a cam edge 293 and a locking bail 275 operated thereby to lock the keys against depression when the control slide is in all positions except Register and Adding positions.

A totalizer engaging control segment 294 (Fig. 9) is differentially positioned, under control of the control slide 72, by means to be presently described. The segment 294 is free on the shaft 221 and carries a stud 295 which projects through a slot 296 in an arm 297 secured on a shaft 298 journaled in the plates 63 and 64. Also secured on the shaft 298 is an arm 299 having in the upper end thereof a slot which engages a stud 300 in the slide 72.

Moving the control slide 72 from the "Register" position to any one of its other positions of adjustment causes the arm 299, shaft 298, and arm 297 to rock counter-clockwise, whereupon the control segment 294 will, through the stud 295 and slot 296, be positioned accordingly. The segment 294 has a control portion 214 and opposed projections 301 and 302 extending into an opening formed in said segment which projections will, upon certain adjustments of the segment 294, be placed opposite a stud 218 (Fig. 14) and cooperate with the latter to control the engagement and disengagement of the selected totalizer with the amount actuators, as will be more fully described hereinafter.

Pivots mounted on a stud 303 on the segment 294 (Figs. 9 and 14) is an auxiliary control member 304 having a slot 309 which is concentric with the stud 303 and in which stud 295 may operate to allow the auxiliary control member to pivot about the stud 303. A spring 307 connected to a stud 414 in the upper end of the member 304 and to an extension of the segment 294 normally urges the member 304 clockwise to maintain a stud 308 carried thereby in yielding engagement with the edge of the segment 294. The auxiliary control member 304 has a surface 412 on the upper end thereof which may be engaged by a stud 411 on the control segment 219 to prevent counter-clockwise movement of the auxiliary member 304 about its pivot 303 and thus enables projections 305 and 306 on the auxiliary member 304 to cooperate with the stud 218 in the same manner as projection 301 on segment 294, previously described, to provide additional control over the engaging and disengaging movement of the totalizers.

The segment 294 and the auxiliary control member 304 are moved together as a unit about the shaft 221 by the control slide 72 to bring the projection 305 opposite the stud 218 in Adding operations, and the projection 306 opposite the stud 218 in Register operations.

The form of auxiliary control member 304 shown in Figs. 9 and 14 enables only cash items to be accumulated when the machine is used as a cash register. When it is desired to accumulate charge items as well as cash items, a plate 413 (Fig. 25) may be readily slipped over the pivot 303 and over the stud 414 on the upper end of the auxiliary control member 304. The plate 413 has two control surfaces 415 and 416 which cooperate with the stud 411 on the segment 219 to block the counter-clockwise movement of the auxiliary control member 304 in Charge and Total Charge Item operations of the machine as well as in Cash and Total Cash Item operations.

The control exerted on the totalizer engaging mechanism by these control segments and members will be fully explained hereinafter.

Also secured to shaft 298 (Fig. 18) are control segment 347 and control member 377, which are differentially positioned under control of the control slide 72. These control elements exercise certain controls over the shifting of the totalizers to select one or the other for engagement with the actuators, as will be later described.

Column selection keys

The bank of column selection keys 84 (Figs. 1 and 8) are provided herein for the purpose of controlling the shifting of the printing mechanism to enable printing to take place in different columns on the record material 422 (Figs. 2 and 3). Such columns, in the present instance, have various designations to identify the columns in which items corresponding to different classifications may be printed. The column selection keys 84 may be depressed only when the control slide 72 is in its Register position and when depressed are effective to shift the control plate 235 to release the hook 236 from its related member 237 on the keylock shaft. When no column selection key 84 is depressed, a zero stop mechanism causes the differential mechanism to position the shiftable amount type wheels, together with the corresponding transaction type wheels, ledger number wheels, and type wheels corresponding to the control slide 72, to print in a wide column located on the lefthand side of the record material, shown in Figs. 2 and 3, and identified as column I. Inasmuch as the column selection keys 84, together with the mechanism controlled thereby for shifting the printing mechanism to print in the different columns of the record material, is the same as that shown and described in the above mentioned Carey et al. application, reference is hereby made to such application for a complete understanding of the same.

Printing mechanism

The printing mechanism is fully illustrated and described in the above mentioned Carey et al. application and therefore it is not thought necessary to show or describe it in detail here. What is shown consists of type wheels 421 (Fig. 5) which are adapted to be shifted laterally under the control of the column selecting keys 84 (Fig. 8) to print in different columns on record material 422 (Figs. 2 and 3).

The method of shifting the totalizer wheels to print in different columns on the record material is fully illustrated and described in the above mentioned Carey et al. application. Also the method of adjusting the type wheels embodies an application of the well known Kreider principle of driving mechanism disclosed in the above mentioned Kreider Patent No. 1,693,279. Reference is hereby made to said Carey et al. application and Kreider patent for a full showing and description of these methods and mechanisms.

Indicating mechanism

The indicating mechanism is fully shown and described in the Carey et al. application herebefore referred to, and therefore it is not described herein. A segment 423 (Fig. 5) serves to adjust the proper indicator, which segment is set through the link 160 and beam 157, to a position corresponding to the key depressed.

Totalizer mechanism

The machine illustrating the invention has two

totalizers, namely an item totalizer and a group totalizer. When the machine is used as a cash register the item totalizer is employed to accumulate the total of a plurality of items constituting a multiple item transaction, from which totalizer said amount is transferred to the group totalizer, which, in the present embodiment, maintains a running total of all cash items registered in the machine. When registering a single item cash transaction, the amount is entered directly into the group totalizer. However, when the machine is used as an adding machine, only the item totalizer is used.

The item totalizer includes six totalizer wheels 170 (Figs. 5 and 22), and the group totalizer comprises a like number of totalizer wheels 171. Five of the totalizer wheels of each totalizer correspond to the five amount banks, and the sixth order wheel is used to receive overflow amounts from the fifth order. The totalizer wheels 170 and 171 are rotatably mounted on a totalizer shaft 174 (Figs. 5 and 22) which is shiftably supported in a framework to enable the wheels 170 or 171 to be moved opposite the actuators to select one or the other of the totalizers for actuation. The framework is shiftable under control of the control slide 72 and the transaction keys 83, to properly engage the selected set of totalizer wheels with and disengage said wheels from their corresponding actuators, which actuators are similar in every respect to the actuator 123, explained above in connection with the ten-cent bank of amount keys (Fig. 5).

The shiftable totalizer framework comprises left and right plates 175 and 176 (Figs. 11, 12, 19, 20 and 22) which support the totalizer shaft 174, an engaging shaft 177, and a tie rod 178, which secures said plates in fixed relationship to each other. The totalizer shaft 174 is slidably mounted at each end on trunnions 179 and 180 secured in the plates 175 and 176, respectively. The engaging shaft 177 extends through the end plates 175 and 176, and is rotatably mounted therein. The plates 175 and 176, in turn, are shiftably mounted in the machine by means of slots therein engaging studs 181 and 182 secured in the frames 60 and 61, respectively, and by means of the ends of the shaft 177, which engage, respectively, slots 183 in a pair of totalizer framework support plates 184, which plates are removably attached to the frames 60 and 61 by means of slots in the extensions thereof coacting with studs 185 and by means of screws 186. As shown in Fig. 12, which shows the right-hand plate 184, plates 184 have therein identical camming slots 187, which cooperate with rollers 188 carried by arms 189 secured to the shaft 177. When shaft 177 is rotated clockwise by means hereinafter described, the rollers 188 will travel in the slots 187 and will cause the totalizer to be shifted into engagement with the actuator. Roller 188 also engages a cam slot 190 in arms, as 191 (Fig. 11), to control the movement of the aliner 192. Arms, as the one shown at 193 in Fig. 13, are loosely mounted on tie rod 178 and provide support for the aliner at points intermediate its ends. The construction and operation of the item and group totalizers are similar to the construction and operation of the totalizer shown in Figs. 19 and 22 of the before-mentioned Carey et al. application, and reference may be had thereto for a more complete showing and description thereof.

Secured to the right-hand end of the shaft 177 (Figs. 12 and 14) is an arm 196 to which is pivoted the upper end of an actuating link 197 by which the shaft 177 may be operated to cause

the selected totalizer to be engaged with and disengaged from the amount actuators at proper times in adding, sub-total, and total taking operations. Link 197 may be selectively coupled to its driving means by means which are to be described hereinafter and which are operated under control of the control slide 72 and the transaction differential mechanism.

TOTALIZER ENGAGING MECHANISM

The totalizer engaging mechanism of the instant machine enables the selected totalizer to be engaged with and disengaged from the amount actuators at the proper time in the various types of operation which may be performed by the machine.

Secured to the right-hand end of the shaft 177 (Figs. 12 and 14) is the arm 196, to which is pivoted the upper end of the actuating link 197. The actuating link 197 has an inverted T-shaped slot 385 in its lower end, into which slot projects a stud 386 carried by a cam lever 387 free on the stud 208 carried by the main frame 61.

The cam lever 387 carries rollers 388 and 389, which cooperate, respectively, with the peripheries of companion plate cams 390 and 391 secured to the main shaft 79. During each operation of the machine, the cams 390 and 391 cause lever 387 to make two excursions of movement, each of which excursions consists of a counter-clockwise movement from the position shown in Fig. 14 and a return to this position. Lever 387 makes its first counter-clockwise movement before the amount actuators 123 are moved clockwise from their home positions and remains in its moved position until these actuators have completed their clockwise movement, after which the lever is returned to its home position. The second counter-clockwise movement of lever 387 occurs before the amount actuators begin their return movement counter-clockwise. Lever 387 will remain in its moved position until these actuators have been returned to normal position, after which lever 387 is returned to its home or normal position.

If the actuating link 197 is in the position shown in Fig. 14, the cam lever 387 will not cause any movement of the actuating link 197, because the stud 386 will operate idly in the upwardly-extending portion of the slot 385 in the link 197. When the link has been pivoted either clockwise or counter-clockwise to bring the stud 386 into the right-hand or left-hand branch of the slot 385, the counter-clockwise movement of the cam lever 387 will cause an upward movement of the link 197, which, through arm 196, will cause a clockwise movement of the shaft 177 to cause the rollers 188 on arms 189 to cooperate with slots 187 to engage the totalizer with the amount actuators 123. Return movement of the cam lever 387 will cause the actuating link 197 to be shifted downwardly to its normal position to disengage the totalizer from the actuators. A stud 194 carried by the actuating link 197 cooperates with the extension 223 of the auxiliary frame 64 to prevent unintentional upward movement of the actuating link 197 when the link is in the position shown in Fig. 14 and to prevent the link from being shifted to disengage the right-hand or left-hand branch of the slot 385 during any upward excursion of the link 197.

The actuating link 197 may be pivoted about its connection with the arm 196 to cause the right-hand and left-hand branches of the slot 385 selectively to engage the stud 386 to enable

the link 197 to be actuated thereby. This pivotal movement of the link 197 is controlled by the control slide 72 and by the transaction keys 83 according to the type of operation being performed by the machine. The manner in which the transaction keys and the control slide control the positioning of link 197 will now be explained.

The actuating link 197 carries a stud 198, which cooperates with a slot in a link 199 (Figs. 14 and 17). Link 199 is pivotally supported at its left end by an arm 200 carried by a stud 201 in the frame 61 and is pivotally connected at its right end to a shifting lever 202, by which it may be shifted and, through the engagement of stud 198 with the slot in link 199, cause the actuating link 197 to be pivoted to effect engagement of the right-hand or left-hand branch of the slot 385 in the link 197 with the stud 386 on the cam lever 387.

The upper end of lever 202 (Figs. 10 and 14) is pivotally supported by a stud 203 in the lower end of a lever 204, which is free on the stud 205 in the frame 61. A link 206 connects the upper end of lever 204 to an upper extension of a cam lever 207 free on the stud 208. The lever 207 carries rollers 209 and 210 (Fig. 16), which cooperate, respectively, with the peripheries of companion plate cams 211 and 212 secured to the main shaft 79, which cams receive one complete clockwise rotation during each operation of the machine. The cams 211 and 212, during each rotation thereof, will rock the cam lever 207 and through the link 206, the lever 204 first clockwise from home position before the amount actuators move from their home position, then rock lever 204 counter-clockwise past home position after the amount actuators have completed their clockwise movement, and finally rock lever 204 clockwise to home position after the amount actuators have been restored to their home position.

A stud 397 near the lower end of lever 202 is engaged by a pair of arms 398 and 399, which are pivoted on a stud 400 in the auxiliary frame 64 and urged by spring 401 into engagement with a stud 402 in the frame 64. The arms 398 and 399 tend to maintain the lower end of lever 202 in its neutral or home position, as shown in Fig. 14.

The stud 218, carried by lever 202, is adapted to cooperate with high and low control surfaces on control segments 219 and 220, which are set according to the transaction keys and with high and low control portions on the control segment 294 and the auxiliary control member 304, which are set according to the position of the control slide 72.

The operation of the lever 202 is as follows:

If the stud 218 is not blocked against lateral movement by a high control position on one of the control segments or the control member, clockwise and counter-clockwise movements of the lever 204 will cause the lever 202 to pivot idly about the stud 397, which is yieldingly held in neutral position by the arms 398 and 399.

If the stud 218 is blocked from movement to the left during the initial clockwise movement of lever 204, lever 202 will rock counter-clockwise about the stud 218 and will cause the stud 397 and the lower end of lever 202 to move to the right against the tension spring 401. This movement of the lower end of lever 202 will, through the link 199, shift the actuating link 197 to engage the left-hand branch of the slot 385 with the stud 386 and enable the link 197 to be oper-

ated thereby during the first oscillation of the cam lever 387. The stud 218 is blocked against movement to the left in all total and sub-total operations to cause the engagement of the totalizer with the amount actuators 123 before these actuators move from their home position and to cause the totalizer to be disengaged from the actuators after the actuators have completed their clockwise movements.

In total and sub-total operations the totalizer wheels control the extent of movement of the actuators from their home positions in the same manner as disclosed in the above-mentioned Carey et al. application to which reference may be had for details of this operation.

The movement of the link 199 to the right will also shift the link 195 to remove the zero stops from the differential mechanism during total and sub-total taking operations, as fully described in the above-mentioned Carey et al. application, to which reference may be had for the details of this phase of the operation.

After the lower end of lever 202 has been shifted to the right and lever 204 begins its counter-clockwise movement, the arm 398 will act on the stud 397 to move the lower end of the lever 202 back into its normal position.

If the stud 218 is blocked from movement to the right during the counter-clockwise movement of lever 204, lever 202 will rock clockwise about stud 218 and will cause the stud 397 and the lower end of the lever 202 to move to the left against the tension spring 401. The movement of the lower end of lever 202 to the left will shift the link 197 and cause the right-hand branch of slot 385 to engage the stud 386 on the cam lever 387 to enable the link 197 to be operated thereby during the second oscillation of the cam lever 387. The stud 218 is blocked against movement to the right in all adding operations, sub-total operations, and certain total transfer operations to cause a totalizer to be engaged with the actuators after the actuators have completed their clockwise movement and to be disengaged from the actuators after the actuators have completed their counter-clockwise or return movement to home position.

During the final clockwise movement of lever 204, the arm 399 restores the lower end of the lever 202 to normal position so that at the end of the operation the lever 202 will occupy its normal or home position, as shown in Fig. 14.

The specific controls of the engaging mechanism which are involved in representative types of operation of the machine will be explained more fully hereinafter.

TOTALIZER SELECTING MECHANISM

Novel means is herein provided for shifting the totalizers laterally to selectively control which totalizer is to be engaged with the amount actuators 123. This means is actuated under control of the control slide 72 and the transaction keys 83 (Figs. 1, 6 and 9).

As previously mentioned herein, the totalizer wheels 170 and 171, forming the item totalizer and the group totalizer, respectively, are rotatably mounted on the shaft 174 (Fig. 22) which is adapted to be shifted laterally to position the totalizer wheels of either of said totalizers in alignment with the amount actuators 123, preparatory to engaging said wheels with the actuators. Also pinned to the shaft 174 and slidably mounted on the trunnion 180 is a block 314 (Figs. 18, 19, 20 and 22). The block 314 is pro-

vided with a groove 315 which is engaged by a stud 316 carried by an arm 317 pivotally mounted in a split stud 318, carried by the frame 61. The arm 317 also carries a second stud 319 which coacts with an irregularly shaped cam slot 320 (Figs. 19 and 22) formed in a slide 321, which slide is bifurcated at its front and rear ends to embrace studs 322 and 323 in the frame 61. When the arm 317 is in its normal position, as viewed in Figs. 19 and 22, the stud 319 will be located in the forward end of the slot 320. When in this position, the arm 317, through the coaction of the stud 316 with the groove 315 in the block 314, positions the shaft 174 so that the totalizer wheels 171 of the group totalizer are in proper alignment for engagement with the amount actuators 123.

The slide 321 is adapted to be shifted forwardly, under control of the control slide 72 and certain of the transaction keys 83, whereupon the arm 317, through the coaction of the cam slot 320 with the stud 319, will be cammed in a clockwise direction. When this occurs, the stud 316, being in the groove 315, will shift the block 314 and shaft 174 toward the left to position the item totalizer wheels 170 in proper alignment for engagement with the amount actuators 123. The means for shifting the slide 321 will now be described.

Pinned to the shaft 331 (Figs. 20 and 22), journaled in the totalizer frame supporting plates 184 which are fastened to the side frames 60 and 61, is an arm 332 carrying a stud 333 which projects through an aperture in the slide 321. Also pinned to the shaft 331 is another arm 334 carrying a stud 335 by which a member 336 is pivotally connected to the arm 334. The member 336 normally rests on a stud 337 carried by the frame 64 and may be shifted from its normal position, as viewed in Fig. 20, toward the left, by means to be presently described, and through the train of mechanism above described impart a similar shifting movement to the slide 321. Such movement of the slide 321, as previously explained, results in the shifting of the shaft 174 to position the item totalizer wheels 170 in proper alignment for engagement with the amount actuators 123.

When the member 336 is shifted to the left to cause the item totalizer to be aligned with the amount actuators 123, the lower surface of the member 336 will move beyond the stud 337, and the member 336 can, unless otherwise held elevated, drop in front of the stud 337 and lock the slide 321 in its forward position to maintain the item totalizer in alignment with the amount actuators 123. A stud 357 (Figs. 18 and 21) carried by the member 336 extends through a slot 356 in an arm 348 pivoted on a stud 350 in the auxiliary frame 64, and enables this arm to control whether or not the member 336 will pivot about the stud 335, and also enables arm 348 to raise the member 336 from in front of the stud 337 to allow the member 336 to be shifted to the right to shift the item totalizer out of alignment with the actuators. The arm 348 is urged counter-clockwise about stud 350 by means of spring 349, but the position of the arm 348 is controlled by the segment 219 according to the transaction key 83 depressed. In the disclosed embodiment, the arm 348 will be positioned in its upper position by the engagement of the stud 355 with the high portions of the periphery of segment 219, which high portions are located at all positions except those which are effective when no transaction key is de-

pressed, and when the Sub-Total and List keys are depressed.

A spring 338 (Fig. 18), which is fastened to stud 357 and to the stud 356 fastened to auxiliary frame 64, urges the member 336 to the right to assist restoring the member 336 in this direction.

Means is provided for normally latching the member 336 (Figs. 18 and 20) against left-hand movement to aline the item totalizer with the actuators, said latching means being rendered ineffective by the Total Charge List, Total Cash List, Sub-Total, and List keys 83 (Figs. 1 and 6) and by the control slide 72 when it is in adding position.

An arm 359 (Figs. 18 and 20), pivoted on the stud 365, is urged counter-clockwise by spring 360 until a projection thereon engages a stud 367 on the auxiliary frame 64. A stud 361 on the arm 359 extends in front of a hook 362 on the member 336 and prevents any unintentional movement of the member to the left. Arm 359 is rocked clockwise by a stud 358 on the control segment 219, which stud cooperates with a surface 366 on the arm when the segment 219 is positioned under control of the Total Charge List, Total Cash List, Sub-Total, or List keys, and said arm is also rocked clockwise by the extension 379 of the control member 377 which engages a stud 380 on the arm when the control slide 72 is in Adding position.

The means for shifting the member 336 to the left from its normal position and back to its normal position are shown in Figs. 10, 14, 16 and 18, and will now be described. Freely mounted on the stud 203, carried by the lower end of lever 204 is a lever 343 which has on its upper end a stud 344 which is adapted to selectively engage vertical surfaces 345 and 369 on the member 336 to shift the member respectively to the left and to the right. The lever carries near its lower end a stud 346 which is adapted to coact with a pair of control segments 347 and 363.

As explained earlier herein, the lever 204 is pivotally mounted on a stud 205 on the main frame 61. During each operation of the machine, the pair of cams 211 and 212 (Figs. 16 and 18) are effective through the cam lever 207 and link 206 to impart to the lever 204 first a clockwise movement from its home or normal position, then a counter-clockwise movement past its home position, and finally a clockwise movement back to its home position.

As the lever 204 partakes of these movements, the stud 203 in the lower end thereof will move to the left, then to the right, and finally back to the left and will tend to move the lever 343 in these directions. If the stud 346 in the lower end of lever 343 is blocked against movement in either direction, the stud 203 will cause the lever 343 to pivot about the stud 346 and be effective, through the engagement of stud 344 in the upper end of the lever 343 with the surfaces 345 and 369 on the member 336, to shift the member 336 and the slide 321 to the left and right. However, if the member 336 has been previously shifted to the left, and the rear end thereof has dropped down in front of stud 337, this driving movement of lever 343 will be ineffective to further shift the member 336.

If the stud 346 in the lower end of lever 343 is free to move, then the stud 203 in its movements to the left and right will cause the lever 343 to operate idly without imparting any shifting movement to the member 336.

The blocking of the movement of stud 346 is

effected by the control segment 363, which is set by the transaction differential mechanism, and by the control segment 347 which is set by the control slide 72.

As explained earlier herein, control segment 363 is connected to the control segment 220 by a stud 364, and is moved with the segment 220 when the segment 220 is positioned from shaft 221 by means of the connecting link 224 between the control segment 219 and segment 220. Control segment 363 has an arcuate portion 368 which may be positioned opposite the stud 346 to block the movement thereof to the left and cause stud 344 to shift the slide 336 to the left to aline the item totalizer with the amount actuators 123. In the present embodiment, the portion 368 will be opposite the stud 346 when any one of the Total Charge List, Total Cash List, Sub Total or List keys is depressed.

Control segment 347 is pinned to shaft 298 which is differentially positioned by the control slide 72. A cut-away part of this control segment provides an arcuate surface 370 which blocks the movement of the stud 346 to the right in all positions of the control segment, and also provides a control surface 376 which prevents the leftward movement of the stud 346 when the control slide is in Adding position.

The spring 349, which is connected to arm 348, is also connected to lever 343 and urges the lever 343 counter-clockwise to cause the stud 346 to be normally held in yielding contact with the control surface 370 in the control member 347.

The shifting of the totalizers to selectively aline either the item or group totalizer with the actuator segments 123, therefore, is jointly controlled from the control side 72 and the transaction keys 83 according to the particular operation being performed.

The manner in which these controls are coordinated with other controls during various representative operations of the machine will be explained hereinafter.

OPERATION

The coordination of the operation of the totalizer selecting mechanism and the totalizer engaging mechanism will be clear from the following summary of the effect of the controls on these mechanisms during different types of operation of the machine.

CASH REGISTER

When it is desired to have the machine function as a cash register, the control slide 72 (Figs. 1 and 9) is moved to its Register position. While the control slide remains in this position the machine may be operated to perform various operations under control of the transaction keys 83 which control the proper selection of the totalizers and the engagement of the totalizers during these operations of the machine. The controls which are effective in the operations controlled by the various transaction keys will now be explained.

Single item transaction—Cash

When the machine is operated with the Cash or the ninth key in the transaction bank depressed, the transaction differential will position the control segment 219 (Fig. 21) with a high portion opposite the stud 355 on the arm 348 and will position the control surface 368 (Fig. 18) of the control segment 363 below the stud 346 so that during the first clockwise movement of lever 204 the shifting lever 343 will operate idly and will

allow the group totalizer to remain opposite the actuator segments.

Control segment 219 (Fig. 14) will have a high portion of its lower control surface opposite the stud 218 and the control segment 220 will have moved below the stud 218. These controls will not block the movement of the stud 218 during the first clockwise movement of lever 204 but will block the movement of stud 218, after the stud 218 returns to the position shown in Fig. 14, during the counter-clockwise movement of lever 204, and thereafter will shift the actuating link 197 to the left to couple the link 197 to the cam lever 387 during the second excursion of the cam lever to cause the group totalizer to be engaged with the actuators during their return stroke.

Therefore, in an operation in which the Cash key is depressed, the group totalizer remains in alignment with the actuators and will be engaged with the actuators in add timing to cause the amount set up on the keys to be entered therein.

Single item transaction—Charge

In the embodiment of the machine shown in Figs. 9 and 14 only cash items are entered into the group totalizer.

When entering a single item charge transaction, the amount of the item is printed and set up on the indicators but is not entered into the group totalizer since charge amounts are not to be included in the running total which is accumulated in the group totalizer.

When the machine is operated with the Charge or eighth key in the transaction bank depressed, the transaction differential mechanism will cause the control segment 219 to be positioned with a high portion opposite the stud 355, and will cause the control surface 368 on the control segment 363 to be positioned below the stud 346 so that during the first clockwise movement of lever 204 the shifting lever 343 will operate idly and the group totalizer will remain opposite the actuators.

The control segment 219 will have a low portion opposite the stud 218 and the control segment 220 will have moved below the stud 218. The projection 306 on the auxiliary control member 304 will be opposite stud 218 but the auxiliary control member 304 will be free to rock counter-clockwise. When lever 204 is rocked clockwise and counter-clockwise stud 218 will not be blocked from movement in either direction and the actuating link 197 will not be coupled to the cam lever 387 to be operated thereby to engage the totalizer with the actuators.

In this operation, although the group totalizer is selected for engagement with the actuators, it will not be engaged therewith and no entry will be made therein.

Single item transaction—Received on Account

Amounts which are received on account are cash amounts and are also accumulated in the group totalizer.

In an operation of the machine with the Received on Account or seventh key in the transaction keyboard depressed, the transaction differential mechanism will position control segment 219 to bring high portions opposite studs 355 and 218 and will position control segments 220 and 363 with their control surfaces below the studs 218 and 346 respectively. When the lever 204 is oscillated, the shifting lever 343 will make an idle operation and the group totalizer will be retained opposite the actuators.

As the lever 204 is rocked clockwise, the left-

ward movement of stud 218 is not blocked but when the lever 204 is rocked counter-clockwise the movement of stud 218 to the right will be blocked by the high portion of the control segment 219 and will cause the actuating link 197 to be coupled to the cam lever 387 during the second excursion thereof to cause the group totalizer to be engaged with the actuators during their return movement to cause an additive entry therein.

Single item transaction—No Sale and Paid Out

In an operation in which either the No Sale or the Paid Out key, which occupy respectively the fifth and sixth positions in the transaction bank, is depressed, the control segment 219 will be moved to positions 5 or 6 and will present high portions of the upper control surface opposite the stud 355 and low portions opposite the stud 218. The control segments 220 and 363 will move below the studs 218 and 346 respectively. The auxiliary control member 304 will not be blocked against counter-clockwise movement so the projection 306 thereon will not block the movement of the stud 218 to the right.

During the first clockwise and the counter-clockwise movement of lever 204, the shifting lever 343 and the lever 202 will operate idly and will neither shift the totalizers nor cause them to be engaged with the actuators.

In either of these operations no entry is made in the totalizers.

Multiple item transaction—List

Whenever the various items of a multiple item transaction are to be entered into the machine, the List or fourth key in the transaction bank is used instead of the single item keys; namely, Cash, Charge, Received on Account, Paid Out, and No Sale, which latter keys are not used in conjunction with the List key. As explained earlier herein the List key will remain depressed during the entry of all the items of a multiple item transaction until either the Total Cash List or Total Charge List key is depressed. During the first operation in which the List key is depressed, the transaction differential mechanism will move the segment 219 so that the position "4" is in controlling position and will position the control segments 220 and 363 respectively with no blocking portion in front of stud 218 and with a portion of the control surface 368 in front of stud 346.

When control segment 219 is positioned with "4" position on the upper control surface opposite stud 355 (Fig. 21), a low portion will be effective to allow the arm 348 to drop downwardly when the item totalizer is shifted opposite the actuators and will enable the totalizer to be retained in this shifted position by the engagement of stud 337 with the rear edge of the member 336.

The downward movement of the arm 348 positions a stud 378 thereon in front of a surface 374 of an arm 377 secured to the shaft 298 which, it will be recalled, is rotated by the slide 72. The position of the arm 377 in Fig. 18 corresponds to the "Register" position of the slide 72. Therefore with the stud 378 in front of the surface 374 the slide 72 is locked until either the "Total Cash List" or "Total Charge List" key is operated to clear the item totalizer, whereupon the arm 348 is restored to normal, removing the stud 378 from the path of movement of the arm 377.

The control surface 368 on the control segment 363 will be opposite the stud 346 so that upon the initial clockwise movement of lever 204, the

lever 343 will pivot about the stud 346 and the stud 344 in the upper end of lever 343 will engage the surface 345 on the member 336 to shift the member 336 forwardly to rock the shaft 331 counter-clockwise to shift the slide 321 connected thereto forwardly and position the item totalizer opposite the actuators. As the member 336 is shifted forwardly it will ride off the stud 331 and will drop in front of the stud 337 to lock the totalizer in shifted position. When the member 336 has dropped in front of the stud 337, the surface 369 of the member 336 will have dropped below the path of movement of the stud 344 and the rearward movement of the stud 344 during the counter-clockwise movement of lever 204 will have no effect on the slide 336.

During the initial clockwise movement of lever 204, the stud 218 will not be blocked against leftward movement and the actuating link 197 will not be shifted to engaging relation with the cam lever 387. During the counter-clockwise movement of lever 204, however, a high portion of the lower control surface on the control segment 219 blocks the movement of stud 218 to the right and causes the actuating link 197 to be shifted to the left to be coupled to the cam lever 387 during its second excursion of movement to cause the item totalizer to be engaged with the actuators during their return to normal position to enable an additive entry to be made on the item totalizer.

The counter-clockwise movement of the shaft 331 will disable the releasing means for the List key and the key will be retained in its depressed position until an operation in which shaft 331 is rocked clockwise. Due to the fact that the Item key remains depressed during the entire multiple-item entering operation, the various control segments will remain in these set positions and will exert the same control in each of the several entering operations and enable the total amount of the multiple items to be accumulated.

The List key will be depressed in all multiple-item transactions whether they be Charge or Cash transactions.

Multiple item transaction—Sub-Total

After any of the multiple-item entering operations have taken place, the Sub-Total or third key of the transaction bank may be depressed to control an operation in which a sub-total of the amount standing on the item totalizer is removed from the totalizer and used to control the indicating and the printing means to indicate and record the amount and said amount is thereafter returned to the item totalizer so that additional amounts may be added thereto.

When the machine operates with the Sub-Total key depressed the control segments 219, 220 and 363 are moved from their 4 position to their 3 position. The upper control surface of segment 219 still presents a low portion opposite the stud 355 and allows the arm 348 and member 336 to remain in their lower positions to retain the item totalizer in its position opposite the actuators 123. The control segment 363 will again position its control surface 363 opposite the stud 346 on the lever 343. As the lever 204 makes its movements clockwise and counter-clockwise it will cause lever 343 to pivot about the stud 346 but as the item totalizer has previously been shifted into position opposite the actuators these operations of lever 343 will merely be idle ones.

The control segment 219 presents a high portion of its lower control surface opposite stud 218

and the control segment 220 will be moved into blocking relation with the stud 218. During the initial clockwise movement of the lever 204, the control segment 220 will block the movement of stud 218 to the left and will cause the actuating link 197 to be shifted to the right to couple the actuating link with the cam lever 387 for operation thereby during the first excursion thereof. This operation of the actuating link 197 will cause the item totalizer to be engaged with the actuators during the movement of the actuators from home position to cause the amount to be removed from the item totalizer and will cause the item totalizer to be disengaged from the actuators after they have removed the amount from the item totalizer and have completed their movement from home position.

When lever 204 is given its counter-clockwise movement, the movement of the stud 218 to the right will be blocked by the high portion of control segment 219 and cause the actuating link 197 to be coupled to the cam lever 387 for operation thereby during the second excursion thereof to engage the item totalizer with the actuators to enable them to restore the amount to the item totalizer as they return to their home position.

In the sub-total operation therefore, the item totalizer will remain opposite the actuators and will be engaged with the actuators during their movement from and back to their home position.

Multiple item transaction—Total Cash List

If the amounts of a multiple item transaction are cash amounts, the Total Cash List or second key in the transaction bank is depressed to cause the total amount of the multiple item transaction to be cleared from the item totalizer, recorded and transferred to the running total in the group totalizer.

When the machine is operated with the Total Cash List key depressed, the control segment 219 will be positioned with a high portion of its upper control surface opposite stud 355 which will raise the arm 348 and the member 336 to free the member from locking relation with stud 337. The control segment 219 will present a low portion of its lower control surface opposite the stud 218. While the low portion of the control surface of segment 219 is opposite the stud 218 and will be ineffective to block the movement of stud 218, the stud 411 on the control segment 219 will have moved opposite the control surface 412 on the upper end of the auxiliary control member 304, and will prevent the counter-clockwise movement of the member 304 so that the projection 306 thereon will be effective to block the movement of stud 218 and will have the same effect as though a high portion were present on the segment 219.

The control segments 220 and 363 will be positioned in blocking relation to their respective studs 218 and 346.

During the first clockwise movement of the lever 204 the studs 346 and 218 will be blocked against movement. The blocking of stud 346 will cause lever 343 to pivot about stud 346 but since the item totalizer is already opposite the actuators, this movement of lever 343 will be an idle one. The blocking of the stud 218 will cause the actuating link 197 to be coupled to the cam lever 387 to be shifted thereby to engage the item totalizer with the actuators before the actuators move from home position and to disengage the item totalizer from the actuators after the actuators have completed their movements from home

position and have cleared the amount from the item totalizer.

Since the member 336 has been raised to its upper position by engagement of the high control surface on the segment 219 with the stud 355 on the arm 348, the clockwise movement of the lever 343 about the stud 346 as lever 204 is operated counter-clockwise, will enable the stud 344 to engage the surface 369 on the member 336 to shift the member rearwardly to rock the shaft 331 clockwise and move the group totalizer opposite the actuators.

Upon the counter-clockwise movement of lever 204 the projection 306 on the auxiliary control member 304 will block the movement of stud 218 and will cause the actuating link 197 to be coupled to the cam lever 387 for operation thereby to engage the group totalizer with the actuators during their return to normal or home position to cause the additive entry of the multiple item total into the group totalizer.

The rocking of shaft 331 clockwise during this operation re-enables the releasing means for the List key and allows the List key to be released during this operation.

During the Total Cash Item operation therefore the item totalizer has the multiple item total cleared therefrom and transferred to the group totalizer and the Item key is released.

Multiple item transaction—Total Charge List

Multiple items of either cash or charge transactions are entered with the List key depressed but when the items are related to a charge transaction the Total Charge List key must be depressed to obtain the total of these items. When the controls shown in Figs. 9 and 14 are used, the machine is not intended to be used to include charge amounts in the running total.

After the amounts of a multiple item charge transaction have been entered in the item totalizer, the Total Charge List key is depressed. The control segments 219, 220 and 363 will be effective to control the shifting of the totalizers after the total has been removed from item totalizer and will be effective to cause the item totalizer to engage the actuators before they move from their home position in order that the movement of the actuators from their home position can clear the total from the item totalizer. These operations are the same as in the Total Cash List operation given above. In the Total Charge List operation however, the stud 411 on the control segment 219 will not block the counter-clockwise movement of the auxiliary control member 304 and the projection 306 thereon will not be effective to block the movement of the stud 218 and will not cause the engagement of the group totalizer with the actuators during their return movement to home position. Accordingly the amount taken from the item totalizer will not be entered on the group totalizer.

It will be remembered that, in all multiple item transactions, the positioning of the segment 219 (Figs. 18 and 20) under influence of the List, Sub-Total, Total, Total Cash List, and Total Charge List keys 83 (Figs. 1 and 6) causes the stud 358, in cooperation with the surface 366, to rock the arm 359 clockwise to free the member 336 for forward movement.

Charge transactions—Alternate form of control

If it is desired that charge transaction be included in the running total in the group totalizer, the plate 413 (Fig. 25) is placed on the auxiliary

control member 304. The control surfaces 415 and 416 will be engaged by the stud 411 on the control segment 219, when that segment is positioned under control of the Charge, and Total Charge List as well as the Total Cash List keys, and will cause the projection 306 to be effective to block the movement of the stud 218 to the right and cause the group totalizer to engage the actuators to be actuated thereby during their return movement to home position in Charge and Total Charge List operations, in the first instance to accumulate Charge items in the group totalizer and in the second instance to transfer the total amount of Charge items from the item totalizer to the group totalizer.

READ TOTAL

When it is desired to perform a sub-total operation to ascertain the amount which has been accumulated on the group totalizer, the control slide 72 is moved to its Read Total position. When in this position, the control slide 72 positions means which alone control the selecting and engaging mechanisms and no transaction key 83 is depressed.

During this operation, the control segments 219, 220 and 363, which are positioned by the transaction differential mechanism, remain in their zero position and are out of blocking relation with the studs 218 and 346. When the control slide 72 is moved to Read Total position it will rock the shaft 298 to position the control segment 347 so that the lefthand cut-away portion of the control surface thereof will not be in blocking relation with the stud 346 in the shifting lever 343. When the lever 204 is given its first clockwise movement, the stud 346 will not be blocked and can move freely to allow the shifting lever 343 to rock idly about the stud 344, and this idle operation will allow the group totalizer to remain opposite the actuators.

As the shaft 298 is moved by the control slide 72, it will cause the arm 297 (Figs. 9 and 14), through the slot 296 and stud 295, to position the control segment 294 with the projections 302 and 301 in blocking relation with the stud 218. When lever 204 makes its first clockwise movement, the stud 218 will be blocked by the projection 302 and the actuating lever 197 will be coupled to the cam lever 387 for operation thereby to cause the group totalizer to engage the actuators before they are moved clockwise and enables the actuators to remove the total from the totalizer and set the printing means and indicator according to the amount of the total. After the actuators have been positioned under control of the group totalizer and have removed the total therefrom, the totalizer is disengaged from the actuators. Upon the counter-clockwise movement of lever 204, the stud 218 will be blocked by projection 301 on control segment 294 and will cause the actuating link 197 to be coupled to the cam lever 387 to be operated thereby to re-engage the totalizer with the actuators before their return movement to home position to enable the actuators to restore the total to the group totalizer.

RESET TOTAL

Whenever it is desired to clear the total from the group totalizer, the control slide 72 is shifted to its Reset Total position. As in the Read Total operation previously described, the transaction keys are not used and the control segments 219, 220 and 363 remain in their zero positions.

Moving the control slide 72 to its Reset Total position will cause the shaft 298 to operate and position the control surface 376 of the control segment 347 below the stud 346. When the lever 204 is operated, stud 346 will not be blocked against leftward movement and the shifting lever 343 will make an idle movement and allow the group totalizer to remain opposite the actuators.

Shaft 298 will be effective through the arm 297, the slot 296 and stud 295, to position the control segment 294 in a position where the control portion 214 is opposite the stud 218. Under these circumstances the stud 218 will be blocked by the control portion 214 of control segment 294 during the first clockwise movement of lever 204 and will cause the actuating link 197 to be coupled to the cam lever 387 for operation thereby to cause the group totalizer to be engaged with the actuators before they are moved clockwise from their home position. The extent of the movement of the actuators from their home position will be controlled by the group totalizer and during this movement the actuators will clear the total amount from the totalizer and position printing and indicating means according to this total. After the total has been cleared from the totalizer, the totalizer is disengaged from the actuators.

During the counter-clockwise movement of lever 204 the stud 218 will not be blocked against movement and the actuating link 197 will not be coupled to the cam lever 387. The group totalizer therefore will not be engaged with the actuators during their return movement to home position and will remain in its cleared condition.

ADDING

When it is desired to have the machine serve as a regular adding machine, the control slide 72 is moved to its Adding position. The machine, so conditioned, can be operated to perform adding operations to accumulate amounts set up on the amount keys and also can be operated to obtain sub-totals and totals of the accumulated amounts. In all operations of the machine as an adding machine, the item totalizer is used and when totals are taken therefrom they are not transferred to the group totalizer which contains the total of amounts involved in transactions which are registered when the machine is used as a cash register. The movement of the control slide to adding position will be effective to unlock the additional row of amount keys 81 for operation as explained fully in the above mentioned Carey et al. application and will also be effective to shift the control detent 292 in the transaction bank of keys to lock all the keys therein, except the Sub-Total, Total Cash List and Total Charge List, against depression and to remove the hooks 227 and 236 from blocking position to allow the machine to be released for operation without the depression of keys in the transaction and column selecting banks of keys. The controls which are effective to control the totalizer selecting mechanism and engaging mechanism in the various ones of the operations which can occur with the control slide in Adding position will now be explained.

Adding operation

When amounts set up on the amount keys are to be entered into the item totalizer, no transaction keys are depressed and the control segments 219, 220 and 363 remain in their zero positions in which the control surfaces thereon will be inef-

fective to block the movement of the studs 218, 346 and 355.

The movement of the control slide 72 (Figs. 9 and 18) to adding position will be effective to rock the shaft 298 to position the control segment 347 with the control surface 376 thereon opposite stud 346, and will position the arm 377 so that a notch 375 is directly beneath the stud 378, and so that the extension 379, coacting with the stud 380, will rock the arm 359 clockwise to free the member 336 for forward or left-hand movement. Movement of the slide 72, as previously described, causes the member 336 to be shifted forwardly to select the item totalizer. Then the spring 349 rocks the arm 348 counter-clockwise whereupon the stud 378 enters the notch 375 of the arm 377, thus preventing any further movement of the slide 72 until a total has been taken by either of the total list keys 83. The arm 297 on the shaft 298 will, through slot 296 and stud 295, position the control segment 294 and the auxiliary control member 304 so that the projection 305 on the member 304 will be moved opposite the stud 218. The movement of the auxiliary control member 304 to this position will move the control surface 412 opposite the stud 411 on the control segment 219, which will remain in its zero position, and the counter-clockwise movement of member 304 about its pivot 303 will be prevented thus enabling the projection 305 to be effective to block the movement of stud 218 to the right.

When lever 204 is given its first clockwise movement, the stud 346 will be blocked by the control surface 376 and the shifting lever 343 will pivot counter-clockwise about stud 346 to cause the stud 344 to engage the surface 345 on the member 336 and shift the member to the left to position the item totalizer opposite the actuators. As the member 336 is shifted to the left, it will drop in front of stud 337 and the surface 369 will be located below the path of movement of the stud 344 when the shifting lever 343 is given its clockwise movement about stud 346 during the counter-clockwise movement of lever 204. This will allow the item totalizer to remain in shifted position where it will be retained until the operation in which the total is cleared from the item totalizer.

The stud 218 will not be blocked during the first clockwise movement of lever 204 and the shifting link 197 will not be coupled to the cam lever 387. The item totalizer will not be engaged with the actuators as they are moved clockwise from their home position under control of the amount keys.

During the counter-clockwise movement of lever 204, the movement of stud 218 to the right will be blocked by the projection 305 on the auxiliary control member 304, and will cause the actuating link 197 to be coupled to the cam lever 387 to be actuated thereby to cause the totalizer to be engaged with the actuators during their return movement to home position to cause the additive entry therein of the amount set on the keyboard.

Sub-Total recording

When it is desired to ascertain the total on the item totalizer and to retain the total in the totalizer in order that further amounts may be added thereto, the Sub-Total or third key in the transaction bank is depressed. The transaction differential mechanism will move the control segments 219, 220 and 363 to their third position, in

which position the control segment 219 will present a low control portion opposite stud 355, and a high portion opposite the stud 218, and the control segments 220 and 363 will be in blocking relation with the studs 218 and 346 respectively. When the control segment 219 is moved from its zero position the stud 411 thereon will be moved out of engagement with the control surface on the upper end of the auxiliary control member 304 and will allow the member 304 to move counter-clockwise about its pivot 303 and render the projection 305 ineffective to block the movement of stud 218; however, at this time the high control portion of the control segment 219 will be in blocking relation with the stud 218.

Since the item totalizer is opposite the actuators and the member 336 is in its lower position, the operation of the shifting lever 343 about the stud 346 during the clockwise and counter-clockwise movements of lever 204, will be idle operations and the item totalizer will remain in this position.

During the first clockwise movement of the lever 204, control segment 220 will block the movement of stud 218 and will cause the actuating link 197 to be coupled to the cam lever 387 to be actuated thereby and cause the item totalizer to be engaged with the actuators before the actuators are moved clockwise from their home positions. The actuators will remove the total from the totalizer during their clockwise movement and will set the printing mechanism and indicating mechanism accordingly. After the actuators have completed their clockwise movement the totalizer will be disengaged therefrom.

When the lever 204 is rocked counter-clockwise, stud 218 will be blocked by the high control portion on segment 219 and will cause the actuating link 197 to be coupled to the cam lever 387 to cause the totalizer to be re-engaged with the actuators before their return movement counter-clockwise to their home position. The counter-clockwise movement of the actuators will restore the total in the totalizer.

Total recording operation

When it is desired to ascertain the total on the item totalizer and to clear this total from the totalizer, either the Total Cash List or the Total Charge List, which are respectively the second and first keys in the transaction bank, is depressed. The controls exerted by these keys are identical so that they will be clear from the description of the controls exerted when one of the keys is depressed.

An operation of the machine with the Total Cash List key depressed will cause the control segment 219 to be positioned with a low portion of its lower control surface opposite the stud 218 and with a high portion of its upper control surface under the stud 355 to raise the arm 348 and member 336, to enable the item totalizer to be shifted from its position opposite the actuators. Control segments 220 and 363 will also be positioned with their control surfaces in blocking relation with the studs 218 and 346 respectively.

As explained earlier herein, when the machine is used as an adding machine, stud 411 is effective to prevent counter-clockwise movement of the auxiliary control member 304 as long as the control segment 219 is in its zero position. Upon the movement of the control segment 219 from its zero position under control of the Total Cash List key, the stud 411 will be moved from engage-

ment with the member 304 and will no longer prevent its counter-clockwise movement.

The initial clockwise movement of lever 204 will cause the shifting lever 343 to pivot about its stud 346 which is blocked by the control surface 376. This movement will be an idle one because the item totalizer has previously been shifted to a position opposite the actuators.

When lever 204 is given its initial clockwise movement, stud 218 will be blocked by control segment 220 and will cause the actuating link 197 to be coupled to the cam lever 387 to be actuated thereby and cause the item totalizer to be engaged with the actuators before the actuators are moved clockwise from their home position. The actuators will remove the total from the totalizer during their clockwise movement and will set the printing mechanism and indicating mechanism accordingly. After the actuators have completed their clockwise movement, the totalizer will be disengaged therefrom.

During the counter-clockwise movement of lever 204, the shifting lever 343 will pivot clockwise about the stud 346 and cause the stud 344 to engage the surface 369 on the member 336 to shift that member to the right to thereby move the item totalizer out of operative position and move the group totalizer opposite the actuators. When lever 204 makes this counter-clockwise movement, the stud 218, due to the low control surface on segment 219 and the pivoting of the auxiliary control member 304 about pivot 303, will not be blocked and the actuating link 197 will not be coupled to the cam lever 387. The group totalizer will not be engaged, therefore, when the actuators return counter-clockwise to their home position.

At the end of this operation the item totalizer will have been cleared of the total and will be in its zero position.

While the form of mechanism herein shown and described is admirably adapted to fulfill the objects primarily stated, it is to be understood that it is not intended to confine the invention to the form or embodiment herein disclosed for it is susceptible of embodiment in various forms, all coming within the scope of the claims which follow.

What is claimed is:

1. In a machine of the character described, the combination of a group totalizer and an item totalizer mounted on a common support slidably mounted in the machine; manually adjustable machine conditioning means; a plurality of manipulative control members; a group of actuators common to both of said totalizers; means capable of actuation to shift said totalizers to align either totalizer with the actuators; slidable means for actuating said shifting means; rockable means selectively rendered effective to move the slidable means forward from its normal position to effect alignment of the item totalizer with the actuators and to move the slidable means rearward to restore the slidable means to its home position and effect alignment of the group totalizer with the actuators; and control means settable by the conditioning means and under control of the manipulative control members to control the effectiveness of the rockable means to shift the totalizers.
2. In a machine of the class described, the combination of a group totalizer and an item totalizer carried on a common axle, slidably supported in the machine; common actuators for said totalizers; manually adjustable machine conditioning means; a plurality of control mem-

bers, set under control of the conditioning means; a pivoted member adapted to be operated to shift said axle to properly aline either totalizer with the actuators; a slidable element operably connected to said pivoted members; shiftable means for sliding said element; and rockable means under control of said control members capable of moving said shiftable means forward from a normal position to effect alinement of the item totalizer with the actuators and capable of moving said shiftable means rearward to return the shiftable means to normal position to effect alinement of the group totalizer with the actuators.

3. In a machine of the class described, the combination of a group totalizer and an item totalizer carried on a common axle slidably supported in the machine; common actuators for said totalizers; manually adjustable machine conditioning means; a plurality of control members settable by the conditioning means; a pivoted member operably connected to said axle and adapted to be actuated to shift said axle to properly aline either totalizer with the actuators; a stud carried by said pivoted member; a slidable element; a cam slot formed in said element and engaging said stud which, when the element is operated, actuates said pivoted member; shiftable means for sliding said element; and means under control of said control members for moving said shiftable means forwardly from a normal position to effect alinement of the item totalizer with the actuators and for moving said shiftable means rearwardly to said normal position to effect alinement of the group totalizer with the actuators.

4. In a machine of the class described, the combination of a group totalizer and an item totalizer carried on a common axle slidably supported in the machine; common actuators for said totalizers; manually adjustable machine conditioning means; a plurality of control members; a pivoted member operatively connected to said axle and adapted to be actuated to shift said axle to properly aline either totalizer with the actuators; a slidable element for actuating said pivoted member; shiftable means for sliding said element; movable means capable of one movement to shift the shiftable means forwardly from normal position to effect alinement of the item totalizer with the actuators and capable of another movement to shift said shiftable means rearwardly to home position to effect alinement of the group totalizer with the actuators; a segment positioned under control of said conditioning means; a second segment positioned under control of said control members; and means on said movable means cooperating with said segments to alternately control the said one and said another movement of said movable means.

5. In a machine of the class described, the combination of a group totalizer and an item totalizer carried on a common axle supported in the machine; common actuators for said totalizer; manually adjustable conditioning means; a plurality of control members; shiftable means; means intermediate said shiftable means and said axle through which said shiftable means can shift said axle to properly aline either totalizer with the actuators; a stationary stud adjacent said shiftable means; rockable means; an element on the rockable means, said rockable means rockable in one direction about said element to shift said shiftable means to aline the group totalizer with the actuators and rockable in another direction about said element to shift said

shiftable means to aline the item totalizer with the actuators; means for imparting movement to said rockable means; a segment positioned under control of said conditioning means; a second segment positioned under control of said control members, said element on said rockable means cooperating with said segments to determine whether the movement imparted to said rockable means shall cause said one or said other movement of the rockable means about said element; a spring urged arm operatively connected to said shiftable means and resiliently urging said shiftable means into engagement with said stud so that when said shiftable means is shifted sufficiently to clear said stud, the shiftable means will be forced in front of said stud and out of the path of said one movement of the rockable means, in which shifted position said stud will retain said shiftable means to thus maintain the item totalizer in alinement with the actuators and render the said one movement of said rockable means ineffective; and means positioned under control of said control members for returning said arm to its normal position, and thus move said shiftable means free of the stationary stud and into the path of said one movement of the rockable means to render said shiftable means free to be shifted by the said one movement of said rockable means to aline the group totalizer with the actuators.

6. In a machine of the class described, the combination of a group totalizer and an item totalizer carried on a common axle slidably supported in the machine; common actuators for the totalizer; manually adjustable machine conditioning means; a plurality of control members; shiftable means; means intermediate said shiftable means and said axle through which said shiftable means can shift said axle to properly aline either totalizer with the actuators; a stationary stud adjacent said shiftable means; a latch normally effective to prevent shifting of said shiftable means; a rockable means; an element on the rockable means rockable in one direction about said element to shift said shiftable means to aline the group totalizer with the actuators, and rockable in another direction about said element to shift said shiftable means to aline the item totalizer with the actuators; means for imparting movement to said rockable means; a segment positioned under control of said conditioning means; a second segment positioned under control of said control members, said element on said rockable means cooperating with said segments to determine whether the movement imparted to said rockable means shall cause one or the other of said movements of the rockable means about said element; a spring urged arm operatively connected to said shiftable means and resiliently urging the shiftable means into engagement with said stud so that when the shiftable means is shifted sufficiently to clear said stud, the shiftable means will be forced in front of said stud and out of the path of movement of the rockable means, in which shifted position said stud will retain said shiftable means to thus maintain the item totalizer in alinement with the actuators and render the said one movement of said rockable means ineffective; and means positioned under control of said control members for rendering said latch ineffective and for returning said arm to its normal position and thus free said shiftable means from the stationary stud and move the shiftable means into the path of movement of the rockable means to ren-

der said shiftable means free to be shifted by the said one movement of said rockable means to aline the group totalizer with the actuators.

7. In a machine of the class described, the combination of a group totalizer and an item totalizer carried on a common axle slidably supported in the machine; common actuators for the totalizer; manually adjustable machine conditioning means; a plurality of control members; shiftable means; means intermediate said shiftable means and said axle through which said shiftable means can shift said axle to properly aline either totalizer with the actuators; a latch normally effective to prevent shifting of said shiftable means to aline the item totalizer with the actuators; means adjustable under control of said conditioning means to render said latch ineffective; a stationary stud adjacent said shiftable means; rockable means; an element on the rockable means, said rockable means rockable in one direction about said element to shift said shiftable means to aline the group totalizer with the actuators and rockable in another direction about said element to shift said shiftable means to aline the item totalizer with the actuators; means for imparting movement to said rockable means; a segment positioned under control of said conditioning means; a second segment positioned under control of said control members, said element on said rockable means cooperating with said segments to determine whether the movement to be imparted to said rockable means shall cause said one or the said another movement of the rockable means about the element; an arm operatively connected to said shiftable means and resiliently connected to said rockable means, which arm, when the shiftable means is shifted sufficiently to clear said stud, will be forced by its resilient connection with said rockable means to move the shiftable means into latching engagement with said stud and out of the path of movement of the rockable means, in which shifted position said stud will retain said shiftable means to thus maintain the item totalizer in alinement with the actuators and render the said one movement of said rockable means ineffective; and means positioned under control of said control members for rendering said latch ineffective and for returning said arm to its normal position and thus free said shiftable means from the stationary stud and move the shiftable means into the path of the said one movement of the rockable means to render said shiftable means free to be shifted by the movement of said rockable means to aline the group totalizer with the actuator.

8. In a machine of the class described, the combination of a totalizer; actuators therefor; means to engage and disengage the totalizer with and from the actuators; a mode of operation control device settable to a plurality of positions; a plurality of manipulative control members; engaging means controlling means including a first element settable into one controlling position by the device but normally ineffective to cause engagement of the totalizer; and a further control element settable under control of the manipulative control members and effective when set under control of one of said manipulative control members to cooperate with the first element and render the first element operable to cause the engaging means to operate, said first element, when set to another controlling position by the control device, cooperating with said further control element to be normally effective to cause the engaging means to operate, but rendered ineffective to

cause the engaging means to operate when said further control element is set under control of said one of said manipulative control members.

9. In a machine of the class described, having a plurality of totalizers; control keys; adjustable machine conditioning means; means for shifting said totalizers to properly aline any desired totalizer with the actuators; means adjustable under control of said keys to control said shifting means to aline one of said totalizers with the actuators; means adjustable under control of said machine conditioning means for controlling said shifting means to aline one of said totalizers with the actuators; means to engage and disengage the properly alined totalizer with and from the actuators; a control member positioned under control of said keys; a control element connected to the control member and positioned thereby in relation thereto; an auxiliary control member settable by the machine conditioning means and normally ineffective; means on the control member engageable with the auxiliary control member to render the auxiliary member effective; and means cooperating with the control member or the auxiliary control member and the control element to control the engaging and disengaging means to cause the properly alined totalizer to be properly engaged with and disengaged from the actuators.

10. In a machine of the class described, having a group totalizer and an item totalizer, the combination of a group of actuators common to both of said totalizers; control keys; adjustable machine conditioning means; means for shifting said totalizers to properly aline either totalizer with the actuators; means adjustable under control of said keys to control said shifting means to aline one of said totalizers with the actuators; means adjustable under control of said machine conditioning means for controlling said shifting means to aline one of said totalizers with the actuators; means to engage and disengage the properly alined totalizer with and from the actuators; a control member capable of various adjustments under control of said control keys; a control element connected to said control member and positioned thereby in relation thereto; an auxiliary control member normally ineffective; means on the control member engageable with the auxiliary control member to render the auxiliary control member effective; means under control of said machine conditioning means for setting said auxiliary control member in position to cooperate with said means on the control member and be effective to supersede the control normally exercised by said control member; and means cooperating with the control member and the control element or the auxiliary control member and the control element to control the engaging and disengaging means to cause the totalizer which has been alined with the actuators to be properly engaged therewith and disengaged therefrom.

11. In a machine of the class described, having a group totalizer and an item totalizer; the combination of a group of actuators common to all of said totalizers; control keys; adjustable machine conditioning means; means for shifting said totalizers to properly aline any desired totalizer with the actuators; means adjustable under control of said keys to control said shifting means to aline one of said totalizers with the actuators; means adjustable under control of said machine conditioning means for controlling said shifting means to aline one of said totalizers with the

actuators; means to engage and disengage the properly aligned totalizer with and from the actuators; a control member capable of various adjustments under control of said control keys; a control element connected to said control member and positioned thereby in relation thereto; means cooperating with the control member and the control element to control the engaging and disengaging means to cause the properly aligned totalizer to be engaged with and disengaged from the actuators at the proper time; a normally ineffective auxiliary control member; means on the control member engageable with the auxiliary control member; and means adjustable under control of said machine conditioning means to move said auxiliary control member relatively to said control member to engage the means on the control member with the auxiliary control member to thereby cause the control member to render said auxiliary control member effective to supersede the control normally exercised by the control member over the engaging and disengaging means.

12. In a machine of the class described, having a group totalizer and an item totalizer, the combination of actuators for the totalizers; means for shifting the totalizers to align any desired totalizer with the actuators; control keys; machine conditioning means; means to engage and disengage the properly aligned totalizer with and from the actuators; a control member capable of various adjustments under control of said control keys for controlling said engaging means; a control element connected to said control member and positioned thereby in relation thereto; an auxiliary control member normally ineffective; means on said control member coacting with the auxiliary control member, when said control member receives a certain adjustment, to render the auxiliary control member effective to supersede the control normally exercised by the latter over the engaging means; means adjustable under control of said machine conditioning means to move said auxiliary control member relatively to said control member to cause the latter to render said auxiliary control member effective to supersede the control normally exercised by the control member; and means cooperating with the control member and the control element or the auxiliary control member and the control element to control the engaging and disengaging means to cause the properly aligned totalizer to be engaged with and disengaged from the actuators.

13. In a machine of the class described having totalizers and differential actuators for the totalizers, the combination of means to engage and disengage the totalizers with and from the actuators; means to operate the engaging means; means to connect the engaging means to its operating means, said connecting means being normally disconnected from the operating means but shiftable to positions to connect the engaging means to its operating means; means, including a free floating lever, for causing the shifting of said connecting means to connect the engaging means to the operating means therefor, said shifting means being normally ineffective to shift the connecting means as long as the floating lever operates idly and is not blocked against movement, but becoming effective when the free floating lever is blocked against movement to cause the connecting means to be shifted to connect the engaging means to its operating means; a first control element settable to different positions in blocking relation to said floating lever; a second

control element settable to different positions, said first and second control elements being settable relatively to each other; and means on the second control element cooperable with the first control element when the control elements are in certain relative positions for rendering the first control element effective to block the movement of the floating lever.

14. In a machine of the class described having totalizers and differential actuators for the totalizers, the combination of means to engage and disengage the totalizers with and from the actuators; means to operate the engaging means; means to connect the engaging means to its operating means, said connecting means being normally disconnected from the operating means but shiftable to positions to connect the engaging means to its operating means; means, including a free floating lever, for causing the shifting of said connecting means to connect the engaging means to the operating means therefor, said shifting means being normally ineffective to shift the connecting means as long as the floating lever operates idly and is not blocked against movement, but becoming effective when the free floating lever is blocked against movement to cause the connecting means to be shifted to connect the engaging means to its operating means; a manipulative control member settable to different positions of adjustment; control keys; a first control element settable into one or another blocking position relative to the floating lever by the control member; a second control element settable under control of the keys and relatively to the first control element; and means on the first and second control elements interacting to control the effectiveness of the first control element to block the movement of the floating lever to cause the engaging means to be connected to its operating means to be operated thereby.

15. In a machine of the class described having totalizers and differential actuators for the totalizers, the combination of means to engage and disengage the totalizers with and from the actuators; means to operate the engaging means; means to connect the engaging means to its operating means, said connecting means being normally disconnected from the operating means but shiftable to positions to connect the engaging means to its operating means; means, including a free floating lever, for causing the shifting of said connecting means to connect the engaging means to the operating means therefor, said shifting means being normally ineffective to shift the connecting means as long as the floating lever operates idly and is not blocked against movement, but becoming effective when the free floating lever is blocked against movement to cause the connecting means to be shifted to connect the engaging means to its operating means; a manipulative control member settable to different positions of adjustment; control keys; a first control element settable by the control member into one blocking position relative to the floating lever but normally ineffective in said position to block the movement of the lever; a second control element settable from a normal position relative to the first control element under control of said keys; and means on the second control element engageable with the first control element, when set to a predetermined position relative thereto under control of one of said keys, to render the first control element effective to block the movement of the floating lever, said first control element, when set to another position by

the control member, cooperating with the means on the second control element in its normal position to be effective to block the movement of the floating lever until said means on the second control element is moved relatively to the first control member and from the normal position of the second control member under control of said one key.

16. In a machine of the class described, the combination of two totalizers mounted on a common axle; actuators for the totalizers; means for shifting the totalizers relatively to the actuators to select either of said totalizers for actuation thereby; means common to both of the totalizers for engaging and disengaging the selected totalizer with and from the actuators; manipulative control elements; means controlled by the elements and common to the shifting means and the engaging and disengaging means for determining which of the totalizers will be selected by said shifting means and for determining the effectiveness of said engaging and disengaging means; a manually adjustable device having several positions of adjustment; and control means positioned by the manually adjustable device and effective when said device is moved to a certain one of its several positions of adjustment to alter the control of the means controlled by the elements over the engaging and disengaging means.

17. In a machine of the character described, arranged for the transferring of totals from one totalizer to another, the combination of two totalizers mounted on a single axle; actuators for the totalizers; amount entering devices to control the actuators to determine the amounts to be entered in the totalizers; a single means to engage and disengage either of the two totalizers with and from the actuators; means to shift the totalizers in relation to the actuators to align the desired one of said totalizers therewith; a first control element; a second control element; and means controlled by the first control element when it is effective to control the totalizer shifting means and the totalizer engaging and disengaging means to align one of the totalizers with the actuators and to control the engaging and disengaging of said totalizer with and from said actuators to effect addition in said selected totalizer, said means also controlled by the second control element when it is effective to further control the shifting means and the totalizer engaging and disengaging means to cause the one totalizer to be aligned with the actuators and to control the engaging and disengaging of said totalizer with and from said actuators to effect the clearing of said totalizer, said means effective thereafter to align the other totalizer with the actuators and to control the engaging and disengaging of said other totalizer with and from said actuators to additively enter the amount cleared from said one totalizer into said other totalizer.

18. In a machine of the character described, the combination of two totalizers; an axle supporting the two totalizers, said axle shiftably mounted in the machine; actuators common to the two totalizers; manually adjustable machine conditioning means; a plurality of control elements; means to shift the axle to align the desired totalizer with the actuators; means, including a member, to operate the shifting means; means adjustable under control of the machine conditioning means and cooperating with the member to control the shifting means to cause one of the totalizers to be aligned with the actuators; and means adjustable under control of the control elements and effec-

tive when the machine conditioning means is in a certain position of adjustment, said means cooperating with the member to control the shifting means to cause the totalizer corresponding to the effective control element to be aligned with the actuators.

19. In a machine of the class described, the combination of a group totalizer and an item totalizer carried on a common axle, said axle slidably supported in the machine; a single set of actuators for the two totalizers; manually adjustable conditioning means; a plurality of control members; shiftable means; means intermediate said shiftable means and said axle, through which said shiftable means may shift said axle to properly align either of the totalizers with the actuators; a fixed stud adjacent said shiftable means; pivoted means rockable in one direction to shift said shiftable means to align the group totalizer with the actuators and rockable in another direction to shift said shiftable means to align the item totalizer with the actuators; a segment positioned under control of said conditioning means; a second segment positioned under control of said control members; means on said pivoted means cooperating with said segments to determine the movements imparted to said pivoted means; a lever operatively connected to said shiftable means; and means resiliently urging said lever to maintain the shiftable means in engagement with said stud, said urging means effective, when said shiftable means is shifted sufficiently to clear said stud, to cause said shiftable means to be moved out of operative relationship with the pivoted means and in front of said stud, in which shifted position said stud will retain said shiftable means to maintain the item totalizer in alignment with the actuators and to maintain the shiftable means out of operative relationship with the pivoted means.

20. In a machine of the class described, capable of transfer total operations, the combination of two totalizers; a shaft supporting the two totalizers, said shaft mounted in the machine for axial sliding movement and for shifting movement parallel to the axis thereof; actuators for the totalizers; means to slide the shaft to align the desired totalizer with the actuators; means to impart two complete shifting movements to the shaft each machine operation to engage and disengage the aligned totalizer with and from the actuators, the first of said movements being in proper timing to clear the aligned totalizer and the second movement being in proper timing to add in the aligned totalizer; a mode of operation control device settable to several positions; a plurality of control elements; control means for the sliding means; a first control means for the imparting means, both of said control means being settable under control of the control elements and effective when set under control of one of said elements to cause one of the totalizers to be engaged with and disengaged from the actuators during the first shifting movement of the shaft to clear said totalizer, and to thereafter cause the sliding means to align the other totalizer with the actuator; and a second control means for the imparting means settable under control of the mode of operation control device, said means effective when said device is in one position of adjustment and coacting with the first control means when it is set under control of said one element to cause the second shifting movement of the shaft to engage and disengage the other totalizer with and from the actuators

in add timing, to add the amount cleared from the one totalizer in said other totalizer, to effect the transfer of a total from one totalizer to another in a single cycle of operation of the machine mechanism.

21. In a machine of the class described, the combination of two totalizers mounted on the same axle; actuators for the totalizers; means to shift the totalizers relatively to the actuators to select the desired one of said totalizers for actuation thereby; means to impart engaging and disengaging movement to the axle to engage and disengage the selected totalizer with and from the actuators; manipulative control elements; a first means controlled by the elements and co-acting with the shifting means and the engaging and disengaging means to determine which totalizer will be selected by said shifting means and to determine the effectiveness of said engaging and disengaging means; a manually adjustable device having several positions of adjustment; and a second control means positioned by the device and effective when said device is moved to a certain one of its several positions of adjustment to alter the control of the first control means over the engaging and disengaging means.

22. In a machine of the character described, the combination of a totalizer; actuators for the totalizer; means to engage and disengage the totalizer with and from the actuators; manipulative control elements; means positioned by the control elements to control the engaging and disengaging means; a manipulative control device; means positioned by the device to control the engaging and disengaging means; and means carried by the means positioned by the control device and positioned thereby, said means rendered effective by the means positioned by the control elements to further control the engaging and disengaging means.

23. In a machine of the character described, the combination of a totalizer; actuators for the totalizer; means to engage and disengage the totalizer with and from the actuator; means to operate the engaging and disengaging means; means normally ineffective to connect the engaging and disengaging means to the operating means; manipulative control elements; a first control means positioned by the elements to con-

trol the effectiveness of the connecting means; a manually operable control device; a second control means positioned by the device to control the effectiveness of the connecting means; and means carried by the second control means and positioned thereby, said means rendered effective by the first control means to alter the control of the effectiveness of the connecting means by said first and second control means to cause the totalizer to be properly engaged with and disengaged from the actuators.

24. In a machine of the character described, the combination of a totalizer; actuators for the totalizer; means to engage and disengage the totalizer with and from the actuators; means to operate the engaging and disengaging means; normally ineffective means to connect the engaging and disengaging means to the operating means; control elements; a first control means positioned by the elements to control the effectiveness of the connecting means; a control member, a second control means positioned by the member to control the effectiveness of the connecting means; and means carried by the second control means and positioned thereby, said means rendered effective by the first control means and coacting with either of said control means to alter the control thereby of the effectiveness of the connecting means to cause the totalizer to be properly engaged with and disengaged from the actuators.

HAROLD O. RANDALL.
JOHN H. MORE,

*Administrator of the Estate of John B. Geers,
Deceased.*

Certificate of Correction

Patent No. 2,450,165.

September 28, 1948.

HAROLD O. RANDALL ET AL.

It is hereby certified that errors appear in the printed specification of the above numbered patent requiring correction as follows:

Column 25, line 4, for "stud 356" read *stud 365*; column 37, line 5, claim 2, for the word "members" read *member*; line 21, claim 3, for "operatably" read *operatively*; and that the said Letters Patent should be read with these corrections therein that the same may conform to the record of the case in the Patent Office.

Signed and sealed this 28th day of December, A. D. 1948.
